UNITED STATES PATENT OFFICE.

ERASTUS WOODWARD, OF SOMERVILLE, MASSACHUSETTS, ASSIGNOR, BY MESNE
ASSIGNMENTS, TO THOMAS G. PLANT, OF BOSTON, MASSACHUSETTS.

HEELING-MACHINE.

958,056.

Specification of Letters Patent.

Patented May 17, 1910.

Application filed July 23, 1906. Serial No. 327,389.

To all whom it may concern:

Be it known that I, ERASTUS WOODWARD, a citizen of the United States, residing at Somerville, in the county of Middlesex, 5 State of Massachusetts, have invented an Improvement in Heeling-Machines, of which the following description, in connection with the accompanying drawings, is a specification, like letters on the drawings 10 representing like parts.

This invention relates to machines for attaching heels to shoes, and is designed to provide various improvements in the general organization and mode of operation of 15 such machines.

An organized machine embodying all the features of this invention is designed to perform three principal offices: to prick the heel; to nail the heel to the shoe; and to 20 spank on a blind toplift. The pricking operation, performed preferably before the heel is assembled with the shoe, comprises preparing a series of holes in a heel for the reception of the heeling nails. The nailing 25 operation comprises driving nails into and through the holes provided by the pricking operation and clenching, upsetting or otherwise securing the nails on the inside of the shoe sole, a portion of each nail usually being left projecting beyond the outer face of 30 the heel. The toplift spanking operation usually practiced comprises applying a toplift to the ends of the nails projecting beyond the outer face of the heel.

The preferred embodiment of this invention hereinafter described is arranged for attaching heels by means of a particular type of nail. These nails are preferably cylindrical in general form and have spatulated points. A short distance from the head end of each nail a projecting annular collar is provided. When a nail is driven through a heel its spatulated point readily clenches inside the shoe and supplies a firm 45 permanent anchorage for the nail. Each nail is driven into the heel until its collar abuts against or seats in the outer surface of the heel and thus when the nail is clenched the heel is positively tied through from face 50 to face. That portion of the head end of the nail which projects beyond the collar, receives the toplift when it is spanked on.

It is a common custom to compress a heel before it is applied to a shoe, and frequently 55 the heel is more or less compressed in con-

nnection with a heeling operation, before nailing it to the heel seat. In such case nails of the type just described serve effectively to bind the heel lifts together in their compressed condition, whereas collarless nails or 60 those having less readily clenchable points might permit the heel to expand when released from positive compression. For example: in the absence of collars or their equivalents on the nails, a heel might expand sufficiently to cover wholly or partly 65 those portions of the nails to which the toplift is intended to be applied; and such expansion might occur before spanking so as to preclude proper attachment of the toplift, or it might occur after spanking so as 70 to force the toplift out of proper engagement with the nails. When a collar or the like is provided, however, a definite length of each nail is preserved for attaching the 75 toplift.

Various other advantages characteristic of this type of nail will appear to those skilled in the art.

In attaching heels with any nails and particularly with these nails, it is considered preferable (though not essential) to provide holes for the reception of the nails, instead of driving them directly through the entire thickness of the heel; and to suit this preference the invention contemplates the employment of suitable pricking means.

In addition to the three principal offices enumerated above, an organized machine embodying all the features of this invention provides for various contributory operations. Means are supplied for holding, also for inserting heels and toplifts in position to be attached. The machine is preferably equipped with automatic nail delivering 80 mechanism. Provision is made for positioning a shoe in its proper relation to the acting parts of the machine. The machine has suitable means for compressing heels before nailing them to shoes, and has also measuring 85 means arranged for measuring the height of each heel as it is about to be attached in order that the subsequent compression shall be uniform on successive heels irrespective of variations in the heights of said heels. 90 100 105

Other features of the machine will be fully explained in the following description.

In the accompanying drawings: Figure 1 is a front elevation of a preferred form of machine embodying this invention, which 110

has been selected for purposes of illustration. Fig. 2 is a rear elevation of the machine shown in Fig. 1. Fig. 3 is a side elevation of the machine as viewed from the right in Fig. 1. Fig. 4 is a side elevation of the machine as viewed from the left in Fig. 1. Fig. 5 is a vertical central section of the machine on the line 5—5 of Fig. 4, looking toward the rear of the machine. Fig. 6 is a horizontal sectional view of the machine on the line 6—6 of Fig. 4 showing a driving shaft, a main shaft and associated elements. Fig. 7 is an enlarged detail rear elevation of the lower part of the machine shown in Fig. 2. Fig. 8 is a detail plan view of certain parts of a starting and stopping mechanism showing a partial horizontal section on the line 8—8 of Fig. 7. Fig. 9 is a detail vertical section of parts of a starting and stopping mechanism, drawn on the line 9—9 of Fig. 7, said line being shown also on Fig. 10. Fig. 10 is a horizontal sectional view on the line 10—10 of Fig. 7, showing elements of a starting and stopping mechanism. Fig. 11 is an enlarged detail front elevation of the lower part of the machine shown in Fig. 1. Fig. 12 is a detail end elevation as viewed from the right in Fig. 9, showing controlling means for a starting and stopping mechanism. Figs. 13 and 14 are respectively diagrammatic views in rear elevation of detached controller ratchets shown also in Figs. 1 and 2. Fig. 15 is a top plan view of a heel holder and a top lift carrier. Fig. 16 is a vertical section on the line 16—16 of Fig. 15. Fig. 17 is a vertical section on the line 17—17 of Fig. 15. Fig. 18 is a rear elevation of the heel holder and top lift carrier shown in Fig. 15. Fig. 19 is a bottom plan view of the heel holder and top lift carrier shown in Fig. 15. Fig. 20 is a vertical section on the line 20—20 of Fig. 15. Fig. 21 is an end elevation of the top lift carrier viewed from the left in Fig. 15. Fig. 22 is a vertical section on the line 22—22 of Fig. 15. Fig. 23 is a plan view of a preferred form of nail block. Fig. 24 is a vertical section of the nail block on the line 24—24 of Fig. 23. Fig. 25 is a detail section of locking means for the nail block drawn on the line 25—25 of Fig. 1. Fig. 26 is a detail end elevation of said locking means as viewed from the left in Fig. 25. Fig. 27 is an enlarged top plan view of a nail hole cylinder shown in Fig. 24 as countersunk in the nail block. Fig. 28 is a side elevation of said cylinder drawn to the same scale as Fig. 27. Fig. 29 is a vertical section of said cylinder taken on the line 29—29 of Fig. 28, a nail driver being shown registering with a nail in the interior of said cylinder. Fig. 30 is a vertical longitudinal section from front to back of the machine, on the line 30—30 of Fig. 2, the rear of the machine shown in Fig. 2 being at the right in

Fig. 30. Fig. 31 is a section similar to that of Fig. 30 showing the relative positions of the parts when holes are being pricked in a heel. Fig. 32 is a section like that of Fig. 31 showing the positions of the parts when a heel is being attached to a shoe. Fig. 33 is a vertical section from front to rear of the machine, on the line 33—33 of Fig. 1, showing in side elevation certain parts shown in section in Fig. 30. Fig. 34 is a detail vertical section on the line 34—34 of Fig. 33. Fig. 35 is a horizontal section of the machine, on the line 35—35 of Fig. 1, showing an auxiliary shaft and elements of a jack actuating mechanism. Fig. 36 is a detail section, on the line 36—36 of Fig. 35, showing a convenient form of means for securing a jack and its actuating means rigidly together. Fig. 37 is a top plan view on an enlarged scale, of parts shown in Fig. 33 comprising a heel anvil table, a jack table and associated elements. Fig. 38 is a front elevation of the parts shown in Fig. 37 (looking upwardly from the bottom of the sheet in Fig. 37), being an enlarged detail of shoe holding means as viewed from the left in Fig. 33. Fig. 39 is an enlarged vertical section cross-wise of the machine, on the line 39—39 of Fig. 33 showing shoe holding means. Fig. 40 is a horizontal detail section on the line 40—40 of Fig. 1 (said line appearing also in Fig. 4) showing a nail carrier in its nail receiving position. Fig. 41 is a section similar to that of Fig. 40 showing a nail carrier in position to deliver nails to a nail block. Fig. 42 is a vertical section of the nail carrier on the line 42—42 of Fig. 40. Fig. 43 is an enlarged detached elevation of that side of the nail supplying mechanism shown at the upper right-hand corner of Fig. 3, a part of the magazine raceway shown in the latter figure being broken away in Fig. 43. Fig. 44 is an enlarged elevation of that side of the nail supplying mechanism shown in Fig. 4. Fig. 44^a is a horizontal detail section on the line 44^a—44^a of Fig. 44. Fig. 45 is an enlarged detail, partly in section, of a nail barrel, a distributor and nail carrier, as shown at the left-hand side of Fig. 43. Fig. 46 is an end elevation of the nail supplying mechanism as viewed from the left in Fig. 43. Fig. 47 is a vertical section of the nail supplying mechanism, on the line 47—47 of Fig. 43, looking toward the left in Fig. 43. Fig. 48 is a detail top plan view of the parts shown in Fig. 45 showing a nail barrel in its normal position of rest. Fig. 48^a is a detail plan view of a nail retaining plate shown also in Fig. 48. Fig. 49 is a view like that in Fig. 48 showing a nail barrel in position to receive a nail. Fig. 50 is a vertical section on the line 50—50 of Fig. 45, showing a nail barrel in elevation in a like position to that shown in Fig. 49 and omitting the parts 664, 666 and 836 shown 130

in Fig. 45. Fig. 51 is a top plan view of the parts shown in Fig. 43. Fig. 52 is a horizontal section on the line 52—52 of Fig. 43. Fig. 53 is a view comparable to Fig. 36 5 showing convenient provision for securing a jack and its actuating means permanently in rigid association. Fig. 54 is a detached view of means possible to be used for converting the machine from a hand measuring 10 machine to an automatically measuring machine.

The specific and illustrative machine shown in the drawings performs the three principal offices of the machine respectively 15 in three cycles. This arrangement as will appear hereinafter is convenient but it is by no means essential.

During the first cycle the heel is pricked. A boy standing on one side of the machine 20 introduces a heel and a toplift to respective carriers and then starts the machine to initiate the pricking operation during which the heel is held stationary while awls descend and make holes for the nails. When 25 the awls have retreated nails are delivered automatically to a nail block into position to be driven; and before the end of the cycle the pricking awls are replaced by drivers which then occupy a proper position for 30 driving the nails during the next cycle. While these various operations are in progress the operator on the opposite side of the machine from the boy is engaged in 35 adjusting a shoe on the heelng jack preparatory to the attachment of the heel, the jack being then in a position easily accessible to the operator. The machine stops automatically at the end of the first cycle and remains at rest until the operator starts it 40 for the second cycle including the nailing operation.

During the period of rest after the completion of the first cycle, the operator pushes the jacked shoe into position under the heel 45 and causes the shoe to be elevated until the heel seat rests against the heel. The shoe is maintained in this position until the beginning of the nailing operation, which next ensues. This preliminary elevation of the 50 shoe will be referred to hereafter as a "heel measuring" operation and its purpose will be more fully elucidated in the appropriate place.

The operator starts the machine for the 55 second cycle. The heel is put under compression and then nails are driven through the pricked holes in the heel and clenched inside the heel seat of the shoe. Thus the heel is secured to the shoe and is no longer 60 dependent upon its carrier, but travels with the shoe and its jack. Before the completion of this cycle, a toplift is carried into position to register with the recently attached heel preparatory to the toplift spanking 65 operation. The machine is stopped automati-

cally at the end of the cycle. At this stage the nails have been driven and clenched; the collars of the nails have been pressed against or embedded in the outer face of the heel; and the head of each nail beyond 70 the collar projects outwardly from the body of the heel in position to be embedded in the toplift by the spanking operation.

Before starting the machine for the spanking operation the operator measures 75 the heel and toplift together, *i. e.*, he elevates the shoe so as to bring the projecting ends of the nails against the face of the toplift. Thereupon he starts the machine and the projecting heads of the nails are pressed 80 into the toplift. During the progress of this cycle the various parts of the machine are returned to their initial positions preparatory to a repetition of the first cycle for 85 pricking a new heel.

While it is considered convenient for the specific machine under discussion to operate in the three distinct cycles just referred to, accompanied by the manual operations performed in the order named, it is to be understood that the particular sequence of operations set forth is not essential and may be altered in various ways. Certain advantages arise, however, from this division of the machine's operation into cycles, and these 90 advantages will be pointed out during the course of the following detailed description.

In order that the operations contemplated by the features of this invention (collectively considered) may be readily understood with relation to the specific machine shown in the drawings, it is expedient preliminarily to elucidate the manner in which the machine is driven and is alternately stopped and started for controlling the operation of the machine in three cycles.

Referring to Figs. 2 and 6, the machine is driven through a belt pulley 60 freely rotatable about a shaft A, the driving shaft of the machine, which extends horizontally 110 across the lower rear part of the machine and is journaled in stationary bearings 61, 62 on the machine frame, and in a bearing 63 supplied by a bracket 64 rigid with the frame. Preferably integral with the belt 115 pulley 60 is a balance wheel 65.

As shown in Fig. 6, the belt pulley 60 has an elongated hub which is mounted to rotate upon a bushing 66 fixed to the shaft A by a set screw. The hub of the belt pulley 60 is confined against axial movement on the shaft, between the inner face of the bearing 63 and an annular flange on the bushing 66. Rigidly secured to the hub of the belt pulley 60 is a clutch member 67 of a positive clutch. 120 A second clutch member 68 is splined to the driving shaft A and is arranged to be freely movable on the shaft toward and from the clutch member 67 for engaging and disengaging the clutch. In the rear of the clutch 125 130

member 68, affixed to the stationary bearing 61, is a friction disk 69. When the clutch member 68 is moved toward the right in Fig. 2 (to the left in Fig. 6) the clutch is engaged and the shaft A is positively driven; when the clutch member 68 is moved in the opposite direction, the clutch is disengaged and the rear face of the member 68 is pressed against the stationary friction disk 69, which serves as a brake to arrest the rotation of the shaft. The clutch member 68 is moved axially on the shaft A to the ends just suggested, by a shipper yoke 70 the arms of which extend into and engage an annular recess 71 on said clutch member. The shipper yoke 70 is fixed upon the end of a main shipper bar 72, which is reciprocated endwise by a starting and stopping mechanism hereinafter described, for engaging and disengaging the clutch. Preferably, the main shipper bar 72 is constantly under the influence of a tractile spring 73, which tends to move said bar to the right in Fig. 2, to engage the clutch. One end of the spring 73 is attached to an adjustable block 74 on the bar 72; and the other end is secured to a stationary pin on the machine frame. Whenever the clutch members are in engagement the driving shaft A drives a main shaft B and an auxiliary shaft C.

Referring to Figs. 1, 5 and 6: the main shaft B is journaled in brackets 75, 76 projecting upwardly from a bottom tie piece D of the machine frame, which is secured between upright standards E, E. Pinions 77, 78 fixed on the driving shaft A mesh respectively with gears 79, 80 fixed on the main shaft B. The relation of the pinions 77, 78 and the gears 79, 80 is such that the main shaft B is driven through one revolution by four revolutions of the driving shaft A.

Referring to Figs. 2, 3 and 7, the auxiliary shaft C is journaled at the rear of the machine above the driving shaft A in bearings 81, 81 on the standards E, E of the machine frame. The auxiliary shaft C is driven by the driving shaft A through the pinion 77 on the latter, intermediate gears 82, 82 (see Fig. 30), and a gear 83 on the shaft C. The intermediate gears 82, 82 are mounted rigidly on a common hub journaled upon a stud which is supported at its opposite ends respectively, by a bracket 84 projecting from the right-hand standard E in Fig. 7, and a yoke 84^a (see Fig. 30), which straddles the shaft A with its crotch resting thereon. The intermediate gears 82, 82 mesh respectively with the pinion 77 and gear 83. The relations of the gears in this train are such that the auxiliary shaft C is driven through one revolution by eight revolutions of the driving shaft A. Thus the auxiliary shaft rotates once during two revolutions of the main shaft B.

The entire operation of the machine from

pricking to spanking, inclusive, consumes two complete revolutions of the main shaft B, and one complete revolution of the auxiliary shaft C, requiring eight revolutions of the driving shaft A. This complete operation of the machine, as already mentioned, is divided for convenience into three cycles, the machine stopping entirely at the completion of each cycle and requiring to be restarted for beginning the next. The first cycle (pricking the heel) consumes one complete revolution of the main shaft B, and one-half a revolution of the auxiliary shaft C. Each of the second and third cycles consumes one-half a revolution of the main shaft B and one-fourth of a revolution of the auxiliary shaft C. It is the office of the specific starting and stopping mechanism, therefore, to permit the machine to be started at three different times for initiating the three cycles respectively; to arrest the machine automatically at the end of the first cycle, when the main shaft B has moved through one complete revolution; to arrest the machine automatically at the end of the second cycle when the main shaft has moved through its next half-revolution; and to arrest the machine at the end of the third cycle when the main shaft has moved through its final half-revolution, when the auxiliary shaft has finished its one revolution during all the cycles, and the operation of the machine is entirely completed.

As regards the preferred form of machine, this invention contemplates that the entire pricking operation shall be conducted under the supervision of the boy who assists the operator; and that the nailing and spanking operations shall be attended to by the operator himself. It is desirable, therefore, that provision be made for permitting the boy to control the machine for the first cycle, and for suspending the operator's control during this time; and also, that provision be made for permitting the operator to control the machine during the second and third cycles, and for suspending the boy's control during this time. As a matter of convenience it is preferred that the operator be stationed upon one side of the machine (hereinafter designated the front of the machine) and that the boy be stationed upon the opposite side (hereinafter designated the rear of the machine). Obviously, means for controlling the first cycle of the machine's operations should be accessible to the boy upon the rear of the machine; and means for controlling the second and third cycles should be accessible to the operator upon the front of the machine. To this end a treadle 85 (see Fig. 6), or other controller, is provided on the rear of the machine for the boy, and a treadle 86 is provided at the front of the machine for the operator.

Referring now to Figs. 7 to 14, inclusive, the manner in which the boy's treadle 85 when depressed initiates the first cycle of operations for pricking the heel, will be first described. As shown in Fig. 7, the treadle 85 is rigidly pinned to the rear end of a treadle shaft 87 journaled in the bottom tie-piece D. The treadle shaft 87 extends to the front of the machine (see Fig. 8) where it is provided with a rigid arm 88. A treadle retracting spring (see Fig. 1) connects this arm 88 with a pin on the bottom tie-piece D, and keeps the treadle 85 normally elevated. The shaft 87 serves also as a fulcrum for the operator's treadle 86 as hereinafter described.

Returning to Fig. 7, the treadle 85 carries a pivoted spring-actuated push-pawl 89 which plays constantly upon the periphery 20 of a controller ratchet 90 fixed upon the rear extremity of a controller shaft 91 mounted in stationary bearings supplied upon the bottom tie-piece D. As clearly shown in Figs. 8 and 9, the controller shaft 91 extends from 25 front to rear of the machine. For the purposes of the specific machine, the controller ratchet 90 (see Fig. 13) is provided with four teeth, each one spaced from the next by the distance of a quadrant. When the push-pawl 89 on the treadle 85 is in engagement 30 with one of the teeth on the controller ratchet 90, depression of the treadle causes said pawl to rotate the ratchet, and thereby to rotate the controller shaft 91. The extent of movement 35 of the treadle 85 (limited by appropriate stops 85^a, 85^b, Fig. 7) is such that a single depression of the treadle will rotate the controller ratchet and its shaft through approximately one-twelfth of a revolution, 40 so that the return of the treadle upon its release does not move the push-pawl 89 sufficiently far to permit it to engage the next following tooth on the controller ratchet. It results therefore, that when the 45 boy's treadle 85 has been once depressed, the boy is deprived temporarily of any control of the machine, since effective engagement of the pawl 89 and ratchet 90 supplies the only means whereby the control of the boy 50 can be communicated to the machine.

Assuming the treadle 85 to be in released position (Fig. 7) and the push pawl to be in effective engagement with a tooth on the ratchet 90, the boy is permitted by depressing the treadle to rotate the controller ratchet and its shaft through a predetermined distance, and thereby to actuate a clutch-engaging mechanism arranged to throw the clutch and start the machine. 55 This clutch engaging mechanism, as exemplified in the accompanying drawings, is intended to release the clutch from a detaining stop and permit the clutch to be thrown in by the tractile spring 73 acting upon the main shipper bar 72 already mentioned.

Referring now to Figs. 8, 9, 10, 11 and 12; the clutch throwing mechanism which will be described for purposes of illustration comprises a scalloped releasing wheel 92 rigid with the controller shaft 91; a releasing plunger 93; and a detaining finger 94. The releasing wheel 92 (see Fig. 12) has its periphery scalloped to provide alternate depressions and projections. When the treadle 85 is depressed, the controller ratchet 90 and the releasing wheel 92 rotate together (both being rigid with the controller shaft) through the distance prescribed by the limited movement of the treadle. This rotation is just sufficient to move the releasing wheel 80 through approximately the distance between the extremities of two adjacent projections on its periphery. Each time the controller ratchet 90 is rotated, one of the projections of the releasing wheel acts in the capacity of 85 a cam to elevate the releasing plunger 93. This releasing plunger 93 (see Figs. 9 and 12) comprises a sleeve 95 having downwardly projecting bifurcations which supply 90 bearings for a pin carrying an anti-friction roller 96. One of said bifurcations provides a yoke which straddles a block 97 loosely mounted upon the controller shaft 91. The sleeve 95 of the plunger receives the lower end of a stud 98 integral with the detaining 95 finger 94, which is thereby pivoted to rock in a substantially horizontal plane. The stud 98 has an annular shoulder which rests against the top of the sleeve 95, and co-operates with a dowel pin 99, in the lower end 100 of the stud between the bifurcations of the sleeve 95, to hold the stud against endwise movement. The stud 98 receives lateral support by passing through a bearing in a stationary bracket 100. This bracket 100 and 105 the yoke straddling the block 97 on the controller shaft 91 serve to prevent any material lateral movement of the releasing plunger. A compression spring 101 encircles 110 a portion of the stud 98, and abuts at its upper end against the stationary bracket 100 and at its lower end against the top of the sleeve 95. Thus, it is apparent that the releasing plunger 93 is capable of vertical reciprocation and has a constant tendency to 115 move downwardly under the influence of the compression spring 101.

As already stated the detaining finger 94 is rigidly mounted upon the upper extremity of the stud 98, and therefore said detaining finger partakes of the vertical reciprocation of the said releasing plunger 93. The releasing plunger 93 is elevated periodically by depression of the boy's treadle 85 (or the operator's treadle 86, as hereinafter 125 explained) which acts through the agency of the controller ratchet 90 to rotate the controller shaft 91 and releasing wheel 92, thereby causing one of the peripheral projections on the latter to act as an elevating cam 130

against the anti-friction roller 96 carried by the releasing plunger. Thus whenever the controller shaft 91 is advanced through one of its steps of rotation, the releasing plunger 93 is elevated and the detaining finger 94 is also elevated. This elevation of the detaining finger serves to release the movable clutch member 68 and to permit the spring 73 to throw it into engagement with the clutch member 67, in a manner presently to be described.

In order that the releasing wheel 92 shall be promptly arrested at the end of each of its steps of rotation, and in order that it shall be held in proper position when at rest, a releasing wheel stop is provided (see Figs. 8 and 12). This stop consists of a roller 102 carried at the end of a spring-pressed plunger 103 and arranged to project into a depression in the scalloped releasing wheel 92 when the latter is at rest (Fig. 12). The plunger 103 rests in a socket provided by a depending arm of the bracket 100, and is acted upon constantly by a compression spring 104, which abuts at its opposite end against an adjusting screw. The plunger 103 has a yoke 105 which straddles a block next to the block 97 (see Fig. 9) on the controller shaft and serves to guide the plunger in its reciprocation. As the scalloped releasing wheel 92 rotates, its projections move the plunger 103 backwardly against its spring; but whenever a depression in said wheel presents itself opposite the plunger the latter is projected forwardly by its spring to force its roller 102 into the depression and thereby stop and hold the said wheel. Thus, whether or not the roller on the releasing plunger 93 is in position to act as a stop for the releasing wheel 92, the latter is always promptly arrested and firmly held by the roller 102 until again positively rotated.

Referring to Figs. 9, 10 and 11, when the releasing plunger 93 and detaining finger 94 are in their lowermost positions, one end of the detaining finger 94 is in engagement with a detaining stop 106 (Fig. 10) mounted on a sleeve 107 which is rigidly and adjustably secured to an auxiliary shipper bar 108. The auxiliary shipper bar 108 is supported so as to be movable endwise in the brackets 75, 76 which supply the bearings for the main shaft B (see Fig. 11). As shown in Figs. 9 and 10, the end of the detaining finger 94 opposite to the end which engages the detaining stop 106, is pivoted on a stud 109 rigid with the main shipper bar 72. With this arrangement the main shipper bar 72 is constantly connected to the detaining finger 94, and the latter has always a tendency to rotate (contra-clockwise as viewed in Fig. 10) under the influence of the tractile spring 73 acting through the main shipper bar. Also under certain

circumstances the detaining finger 94 serves as a connection between the main shipper bar 72 and the auxiliary shipper bar 108 whereby the latter, when moved endwise by a cam, rocks the detaining finger (clockwise as viewed in Fig. 10) and shifts the main shipper bar 72 against its spring 73 to disengage the clutch.

The auxiliary shipper bar 108 is acted upon constantly by a compression spring 110 abutting at one end against the bracket 76 and at its other end against an adjustable collar 111 on the auxiliary shipper bar 108. Thus the compression spring 110 tends to withdraw the detaining stop 106 from its detaining position (see Fig. 10) to release the detaining finger 94 and permit the spring 73 to engage the clutch. Normally when the machine is at rest the parts under discussion occupy the positions shown in Figs. 10 and 11 wherein the detaining finger 94 is in engagement with the detaining stop 106; and the latter has been moved with the auxiliary shipper bar 108 to the left in Figs. 10 and 11, by a first cycle shipping cam 112 on the main shaft B (see also Fig. 1). This first cycle shipping cam acts upon an anti-friction roller 114 on the auxiliary shipper bar 108. Whenever the cam 112 engages the roller 114, the auxiliary shipper bar is moved against the influence of its compression spring 110; and if the detaining finger 94 be then in engagement with the detaining stop 106 on the auxiliary shipper bar, said finger is rocked (clockwise, Fig. 10) so as to move the main shipper bar 72 against the influence of its spring 73 to disengage the clutch and stop the machine.

As shown in Figs. 9 and 10, the cam roller 114 for the auxiliary shipper bar 108 is carried upon an arm 115 projecting from a sleeve rigidly and adjustably secured to said bar. The end of the arm 115 preferably extends into an elongated horizontal groove in the bracket 100. Thus the bar 108 is prevented from rotating so as to affect the engagement between the roller or detaining stop carried by it, with their respective co-acting parts. The shipping cam 112 remains in engagement with the roller 114 after the machine has stopped, thereby maintaining the continuity of the train of mechanism which detains the main shipper bar 72 and holds the clutch disengaged. Evidently, it needs only the interruption of the continuity of this train of detaining mechanism, to release the main shipper bar 72 and permit its tractile spring 73 once more to engage the clutch and start the machine. This interruption is effected, for initiating the first cycle, by the boy who depresses the treadle 85 and thereby rotates the controller ratchet 90, the controller shaft 91, and the scalloped releasing wheel 92 in the manner described. The rotation of the

releasing wheel elevates the releasing plunger 93 and also the detaining finger 94 so as to lift the latter clear of the detaining stop 106. When this has occurred nothing remains to restrain the main shipper bar from being moved by its tractive spring 73 to engage the clutch and start the machine, which in fact ensues.

- The movement of the main shipper bar 72 by the spring 73 rocks the detaining finger 94 on its pivot, so that its free end takes position over the stop 106 and finally rests thereupon thus preventing the spring 101 (see Fig. 9) from returning the finger 94 downwardly to the full extent of its movement. Shortly after the machine is started, the first cycle shipping cam 112 departs from engagement with the roller 114 on the auxiliary shipper bar 108. Thereupon said bar is moved endwise by the compression spring 110 so as to withdraw the detaining stop 106 from beneath the end of the detaining finger 94, which is thereby permitted to drop down into renewed engagement with the detaining stop 106 preparatory to the next action of the shipping cam 112.

It has already been stated that the first cycle consumes one revolution of the main shaft B. When the main shaft completes this one revolution the first cycle shipping cam 112 again engages the roller 114 on the auxiliary shipper bar 108. This engagement of cam and roll moves the auxiliary shipper bar against its spring, and thereby rocks the detaining finger 94 which retracts the main shipper bar 72 against its spring 73 to disengage the clutch and stop the machine. The shipping cam 112 and roller 114 remain in contact to hold the clutch disengaged after the machine has stopped.

When the treadle is depressed for initiating the first cycle, a tooth of the controller ratchet being then in engagement with the push pawl on the treadle, said tooth is moved as far as possible within the limits prescribed by the treadle stops 85^a, 85^b. When the treadle is released and returns to its normal position of rest, the push pawl 89 finds no ratchet tooth in position to be engaged by it and consequently the control of the machine by means of the treadle 85 is temporarily suspended. This suspension continues until the controller shaft is sufficiently rotated (by some means other than the treadle 85) to present another tooth of said controller ratchet in position to be engaged by the push pawl 89 on the treadle 85. The controller ratchet is rotated to this end during the remaining course of operation of the machine by the operator at the front of the machine in a manner about to be described.

As shown in Figs. 8 and 9 the controller shaft 91 extends from the rear of the machine to the front. At its rear extremity

said shaft carries the controller ratchet 90 and at its front extremity adjacent to the operator's treadle 86 said shaft carries a second rigid controller ratchet 116. The ratchet 116 has a series of eight ratchet teeth 70 on its periphery (see Fig. 14) said teeth being arranged in pairs, and each pair being spaced from the next by substantially the distance of a quadrant. A spring actuated push pawl 118 (see Fig. 11) pivoted to the 75 operator's treadle 86 plays constantly upon the periphery of the controller ratchet 116 and at appropriate times in the operation of the machine said pawl is in position to engage a tooth on said ratchet and to rotate the 80 latter upon depression of the operator's treadle 86 in a manner similar to that already described in connection with the boy's treadle 85.

The relation in which the two controller 85 ratchets 90 and 116 are disposed on the controller shaft 91 is of importance. Referring to Figs. 13 and 14, these two ratchets are shown side by side in elevation as viewed from the rear of the machine. If either one 90 of the ratchets there shown be superposed upon the other, so that their vertical lines of reference shall coincide, their teeth will be seen in the relations which they have on the controller shaft 91. That is to say, the 95 boy's controller ratchet 90 has four teeth, each of which is spaced from the next by the distance of a quadrant, while the front controller ratchet 116 has four pairs of teeth, each pair being located (by the proper disposition of the two ratchets on the controller shaft) so as to stand in the quadrant space intervening between two adjacent teeth on the boy's controller ratchet 90. Thus it will be observed that the two controller ratchets are substantially integrated 100 by reason of their rigid association with the controller shaft 91, and thereby said controller shaft is provided with a continuous series of twelve uniformly spaced driving 110 ratchet teeth. Therefore if one or another pawl be driven against said ratchet teeth in succession the controller shaft 91 will be given intermittent rotation through successive steps of uniform length.

Depression of the boy's treadle 85 for initiating the first cycle, rotates the controller shaft 91 through one of these steps, and at the same time (while suspending the boy's control of the machine) it rotates the second controller ratchet 116 so as to bring a tooth thereupon into engagement with the pawl on the operator's treadle 86 permitting the operator thereafter to assume temporary control of the machine. Thus the operator 125 is enabled to start the machine for the second cycle.

The operator's treadle 86 (see Figs. 8 and 11) is loosely fulcrumed upon the treadle shaft 87 which also supplies support for the 130

boy's treadle 85. The operator's treadle is freely rotatable on said shaft within limits prescribed by treadle stops 122, 122. The operator's treadle 86 is held normally elevated by a tractile spring 124 secured at one end to a stationary bracket on the frame of the machine and at its other end to the treadle.

When the first cycle has been completed 10 and the clutch disengaged in the manner already related, the next rotary step of the controller shaft 91 will reengage the clutch and start the machine in exactly the same manner in which it was started for the first 15 cycle. This rotary step of the controller shaft 91 is effected by the operator depressing his treadle 86 which rotates the scalloped releasing wheel 92; elevates the releasing plunger 93 and the detaining finger 94; and thereby disengages the latter from the detaining stop 106 permitting the tractile spring 73 of the main shipper bar 72 to throw the latter, engage the clutch and start the machine.

25 It has already been stated that the second cycle of the machine's operation consumes only one-half of a complete revolution of the main shaft B. Consequently, the first cycle shipping cam 112 is ineffective to stop the 30 machine at the end of the second cycle because said cam acts only at the end of an entire revolution of the main shaft to engage the roller 114 on the auxiliary shipper bar 108 and therethrough to disengage the 35 clutch. An auxiliary clutch disengaging mechanism is therefore introduced, in order to stop the machine at the end of the second cycle when the main shaft has completed but one-half a revolution since beginning 40 the cycle.

Referring to Figs. 7, 9 and 10, the principal instrumentalities of this auxiliary disengaging mechanism comprise a disengaging stop 126; a disengaging lever 128 suitably connected to said stop; and a second 45 cycle shipper cam 130 carried on the auxiliary shaft C. The disengaging stop 126 is supported upon a carriage 132 which is mounted upon the main shipper bar 72 so as 50 to be freely movable endwise. The disengaging lever 128 is fulcrumed on a stud 134 mounted on the frame of the machine; and the lower end of said lever (see Fig. 7) is pivoted at 135 to the disengaging stop 55 carriage 132 so that when the lever is rocked upon its fulcrum said carriage and the disengaging stop 126 are moved lengthwise of the main shipper bar 72. Obviously, if provision be made for causing the main shipper 60 bar 72 to move with the disengaging stop carriage 132, the rocking of the disengaging lever 128 will serve to move the main shipper bar endwise and will thereby effect the engagement or disengagement of the

clutch, as the case may be. Since it is desired that the specific disengaging mechanism under discussion act merely to disengage the clutch, appropriate provision is made for causing the disengaging stop carriage 132 to carry the main shipper bar 72 65 rearwardly (i. e. to the left in Fig. 7) when the former is moved in this direction under proper circumstances by the disengaging lever 128. The provision just referred to consists of a lug 136 (see Fig. 10), integral 70 with the detaining finger 94, which projects into the path traversed by the disengaging stop 126 during the movement of its carriage 132. Except when the detaining finger 94 is in elevated position said lug 136 75 lies in such a position (Fig. 7) that it will be struck by the disengaging stop 126 when the latter is moved to the left in Fig. 7. To all intents and purposes, the detaining finger lug 136 is substantially rigid with the main shipper bar 72 (the detaining finger being pivoted to said bar as already explained) and consequently, when the disengaging stop 126 strikes against the detaining finger lug 136 the former is in effect 80 85 engaging a substantially rigid part of the main shipper bar; and continued movement of the disengaging stop serves to move the shipper bar bodily endwise (to the left in Fig. 7) to disengage the clutch. 90 95

Referring still to Fig. 7, this clutch disengaging movement of the disengaging stop 126 is caused by the second cycle shipper cam 130 acting upon a cam roll 138 pivoted to the upper end of the disengaging lever 100 128. The cam roll 138 is held in engagement with the second cycle shipper cam 130 by a tractile spring 140, secured at one end to a finger 142 integral with the lever 128 and at its other end to the frame of the 105 machine. The spring 140 serves also through the agency of the lever 128 to hold the disengaging stop 126 in its normal inactive position which is conveniently determined by a lug 144, projecting from the 110 frame of the machine, upon which the finger 142 of the disengaging lever abuts when the shipper cam 130 is removed from engagement with the disengaging lever cam roll 138, thereby permitting the spring 140 115 to retract the disengaging lever. When the clutch has been disengaged by the action of the second cycle shipper cam 130 said cam remains in engagement with the disengaging lever cam roll 138 after the machine has 120 come to rest; and this engagement serves, through the intermediation of the disengaging lever and the disengaging stop, to hold the main shipper bar 72 in retracted position against the influence of its tractile 125 spring 73, and thus to keep the machine at rest until in some manner this train of detaining mechanism is disorganized.

It will be observed that the disengaging stop carriage 132 is provided with a recess 146 above the disengaging stop 126. It should be remembered in this connection that 5 the detaining finger lug 136 is in a position to engage the disengaging stop 126 only when the detaining finger 94 is at the lowermost limit of its movement; and it should also be borne in mind that the lug 136 sup- 10 plies the only effective connection between the main shipper bar 72 and the disengaging stop 126 with its associated train of detaining mechanism. Consequently, if the detaining finger 94 be elevated by depressing 15 the treadle the detaining finger lug 136 will be lifted clear of the disengaging stop 126 thereby rendering the latter ineffective and permitting the tractile spring 73 to move the main shipper bar 72 and engage the clutch 20 for starting the machine.

The depression of the operator's treadle for initiating the second cycle rotates the controller ratchet 116 on the front of the machine through one of its usual steps; and 25 when the treadle is released to return to its normal position its push pawl 118 enters into engagement with the next following tooth on the controller ratchet 116, constituting the second tooth of one of the pairs thereon.

30 This movement of the controller shaft 91 is not sufficient to carry a tooth on the rear controller ratchet 90 into position to be engaged by the push pawl on the boy's treadle 83 and, consequently, the boy's control of 35 the machine remains suspended during this time. The operator's treadle 86, however, is in proper condition for permitting the operator to rotate the controller ratchet on his side of the machine to start the machine 40 again for the third cycle. When the operator again depresses his treadle under these circumstances, the detaining finger lug 136 is lifted and the machine is started for the third cycle. In effecting this start, the detaining finger lug 136 (see Fig. 7) is thrown 45 into the recess 146, and when the operator releases his treadle said lug is caused by the coil spring 101 (see Fig. 9) to rest against the bottom wall of said recess in such position 50 that withdrawal of said disengaging stop 126 would permit the detaining finger 94 to return downwardly to the lowermost limit of its movement. Shortly after the beginning of the third cycle, the second cycle shipper cam 130 is removed from engagement 55 with the disengaging lever cam roll 138, and the tractile spring 140 moves the disengaging lever with the result that the disengaging stop 126 is withdrawn (to the right in Fig. 7) and the detaining finger 94 is permitted to drop to its lowermost position, as just suggested. During the entire second cycle and after the beginning of the third cycle, the auxiliary shipper bar 108

at the front of the machine, remains in its 65 retracted position under the influence of its compression spring 110 and consequently, when the detaining finger 94 drops to its lowermost position as just described, the free end of said finger falls into position to be 70 engaged by the detaining stop 106 whenever the auxiliary shipper bar shall be acted upon by the shipping cam 112.

It has been stated hereinbefore that the first cycle consumes one complete rotation 75 of the main shaft, during which the first cycle shipper cam 112 departs from and then returns to its engagement with the cam roll on the auxiliary shipper bar 108. The second cycle is completed and the machine 80 stopped when the main shaft has made its next half revolution only. Hence the shipper cam 112 is not carried into position for stopping the machine. The third cycle, however, moves the main shaft through another 85 half revolution and thereby brings the shipper cam 112 again into position to act upon the auxiliary shipper bar 108 and rock the detaining finger 94 so as to retract the main shipper bar 72 and disengage the clutch, 90 thus stopping the machine at the end of the third cycle. It is evident, therefore, that the cam 112, which has heretofore been designated the first cycle shipper cam, serves 95 also as a third cycle shipper cam.

When the operator depresses his treadle 86 for initiating the third cycle, the push-pawl 118 acts upon the second tooth of a pair on the controller ratchet 116 and the latter is thereby moved through one of its 100 usual steps. When the operator's treadle thereafter returns to its normal position of rest, the push pawl on said treadle finds no tooth on the ratchet 116 in position to be engaged; and consequently, the operator's 105 control of the machine is suspended, as was the boy's after he had depressed his treadle for starting the first cycle. This same depression of the operator's treadle which initiates the third cycle serves to rotate the 110 controller shaft 91 so as to bring a tooth on the boy's controller ratchet 90 into position to be engaged by the push pawl on the boy's 115 treadle so that with the cessation of the operator's control of the machine, the boy's 120 control is renewed to permit him to start the machine again for another first cycle. At the end of the third cycle, the shipper cam 112 returns to its initial position and acts through the agency of the auxiliary 125 shipper bar, the detaining finger and the main shipper bar to disengage the clutch and to hold it disengaged until the continuity of this train of detaining mechanism is interrupted. As just explained, this interruption can be effected only by the boy depressing his treadle, the operator's control of the machine being suspended until the ma-

chine has completed the first cycle and the parts have assumed their proper positions before entering upon the second cycle.

To summarize: The boy, standing at the rear of the machine, after introducing a heel and a toplift as hereinafter described, depresses his treadle to start the first cycle and as soon as this is done the boy loses control over the machine until it is time to start another first cycle. Thus, he is prevented from interfering in any way with the subsequent operations, which are controlled by the operator. During this first cycle, awls are pressed into a heel in order to prepare holes for the reception of the heelng nails. When the main shaft of the machine has completed one revolution, the first cycle comes to an end and the machine is stopped automatically. The first cycle takes place during one revolution of the main shaft B and one-half of a revolution of the auxiliary shaft C. The act of the boy in starting the machine for the first cycle gives over the control of the machine to the operator who, however, is unable to exercise his control to again start the machine until the machine is stopped automatically at the end of the first cycle. The operator then depresses his treadle to start the second cycle during which nails are driven into and through the previously prepared holes and the heel is secured thereby to the shoe. When the main shaft B has completed half a revolution, and the auxiliary shaft C has completed three-fourths of a revolution since the beginning of the first cycle, the second cycle comes to an end and the machine is automatically stopped. The operator still retains control of the machine and by depressing his treadle starts the third cycle, during which a toplift is spanked on the previously nailed heel. During this cycle the main shaft moves through half a revolution, thereby completing its second revolution since the beginning of the first cycle; and the auxiliary shaft makes its last one-quarter revolution, thereby completing one entire revolution since the beginning of the first cycle.

The mode of operation of the preferred form of machine has been set forth above in general terms; and the main actuating elements, together with the manner of controlling them in three cycles, have been sufficiently explained. Hereinafter the construction of the selected machine will be more fully analyzed and the parts will be described somewhat in detail.

For convenience of description, and in order that the operation of the machine in the preferred three cycles may be readily followed during the detailed description, certain parts will be first discussed which perform the principal and contributory offices during the first cycle.

During the pricking operation in the first cycle, the heel is held in position to be operated upon, by a heel carrier F. A series of pricking awls G, located above the heel carrier F, is depressed, each awl passing through a hole in a nail block H and entering the heel. The pressure exerted by the pricking awls G while they are acting upon the heel is sustained by a heel anvil I, which supports the heel between itself and the under face of the nail block H. The heel is introduced to the heel carrier by the boy before he starts the machine for the first cycle, and when in position in said carrier the heel is disposed in its proper relation to the awls G. When the machine is started for the first cycle, the heel anvil I ascends and clamps the heel against the under face of the nail block H which is stationary. While the heel is thus clamped the awls descend, pass through the holes in the nail block and prick the heel. Thereafter the pricking awls G and the heel anvil I retreat leaving the heel still in its carrier, adjacent to the under face of the nail block H.

It has been stated above that, to obtain the best results, particularly when employing the so-called collar nails (which are usually made from wire) as distinguished from cut nails (cut from a metal bar), it is important that the heels be pricked before receiving the nails. This pricking and the insertion of the nails in the heel may be accomplished upon the heelng machine proper which attaches heels to shoes, or upon a separate accessory machine which pricks and loads heels with nails before the heels are positioned in the nailing or attaching machine. In either case the pricking and loading constitute essential parts of heel nailing; and whether these operations be performed separately or as a part of the operation of the attaching machine, the position of the heel with relation to the pricking and loading instrumentalities determines, so to speak, the position which the heel shall occupy upon the shoe. Heel holding means are commonly employed to present heels of different sizes for pricking and loading, and consequently the adjustment of said holding means determines the position which the heel shall occupy upon the shoe. For example, when heels are pricked and loaded separately from a heel attaching machine, one method of positioning the loaded heel with relation to the heel attaching mechanism comprises inserting the heads of the nails in nail driving passages of said mechanism, through which drivers are moved to drive the nails into a shoe sole. The jack of the attaching machine occupies at the moment of nailing a fixed position, though said jack might be arranged for adjustment relatively to the drivers. It follows then, that on such a

machine the position which the heel occupies upon the shoe depends upon the location of the nails in the heel.

As set forth in my Patent No. 570,654, dated November 3, 1896, the proper positioning of a heel for attachment to a shoe is best determined by referring the back of the heel to the rear of the heel seat of the shoe, insuring that such variations and errors as may occur shall affect the breast end rather than the rear of the heel. In other words, the rear of the heel should be positioned, for given styles, invariably with reference to the rear of the heel seat; and all variations or adjustments should be applied to the breast end of the heel. Consequently, in the machine for pricking and loading heels, shown in my said patent, I provided a normally stationary back stop to bring the backs of the heels always to invariable position relative to the pricking and nail inserting means; while the movable jaws or holding devices to grip and square the heel were made to act upon the breast end of the heel. So far as known to me, this was the first instance in the art where movable clamping means were located adjacent to the breast end of the heel, and a normally stationary stop or gage at the back of the heel; prior devices having had the reverse arrangement, namely, a fixed breast stop or gage with movable back stop means for squaring the heel. This principle I have adopted in substance in my present machine, I having used substantially the same form of back stop and breast engaging or clamping means, the heel being centered, not by a "V" at the rear as in other machines, but by and between a pair of jaws acting upon the sides adjacent the breast; and being squared, not by an extended squaring breast gage, but by ears on the centering side engaging members as in my said patent. This arrangement has been found superior to the "V" and the extended squaring breast gage because more certain and accurate. So far, therefore, as the present mechanism follows the mechanism of my said Patent No. 570,654, the former merely employs the latter, with all its attendant functions and advantages, in connection with the pricking and nail inserting means which are applied to and form part of heel attaching machine. In many respects, however, the mechanism of the present machine, while following the general principle of my said patented machine, is in detail and construction superior to that of the latter; and in these respects the claims are to be construed broadly and without limitation to the exact features shown.

In a machine of the type here selected for illustrative purposes, the shoe is heeled sole uppermost because in this position the operator's view of the heel and toplift is not obscured by the shoe, and it is possible for

him to see clearly the heel and toplift before, during, and after they are applied to a shoe, thereby permitting him to determine whether or not they are properly positioned, and whether the nails are sufficient in number and are properly arranged. In the type of machine where the heel is applied with the shoe sole downward, the heel and top lift are substantially concealed from the view of the operator during their application to a shoe, and consequently he is unaware whether they are positioned and nailed as they should be, until after the work has been completed. Heeling the shoe sole upward, however, requires that the heel and top lift be held from above. Carrying means are provided for thus holding the heel and toplift; and in order that they may be readily observed it is important that the carrying means be as narrow as possible from front to back of the machine, in order to permit both the operator at the front and the boy at the rear to see that the heel and toplift are properly inserted and retained in place, and to permit the heel and shoe to be readily and accurately assembled. Also, it is important that the carrying means be so supported as to avoid obstructing the view of the heel and toplift. An important accompaniment of the above is that the adjusting mechanism for varying both the size adjustments and the location adjustments of the heel and the toplift carrying means, should be arranged at the outer sides of the latter so as to permit the heel and toplift to be positioned as near as practicable to each other. This serves to reduce the distance for the carrying means to be moved in order to bring the one into position and the other out of position; and serves also to leave unobstructed the view of the work. At the same time, the adjusting devices should be accessible and of substantial construction.

The construction of the heel carrier F may well be described at this point and since a top lift carrier J is associated with the heel carrier it is convenient to describe them together. The specific heel carrier F comprises clamping jaws 148 and 149, and a heel back-stop 150. Each of the clamping jaws 148 and 149 has a heel-breast stop-face 151 and a side gripping face 152. A heel is engaged endwise between the heel back-stop 150 and the heel breast stop-faces 151; and is gripped laterally between the side gripping faces 152.

It is usually required that a single machine be capable of attaching heels of any desired size or shape; and to this end the present invention contemplates various features of adjustment of the heel clamping jaws and the back-stop. As best shown by a top plan view in Fig. 15, each clamping jaw 148, 149 has an integral arm provided with a rectilinear rack 154; and these racks

are oppositely disposed to engage between them an idle pinion 155, so that if one of the clamping jaws be moved endwise in one direction the other clamping jaw will be moved reciprocally.

Referring to Fig. 15: the two arms of the clamping jaws 148 and 149, are seated for endwise movement in ways 156, 156 formed in a slide 157. The pinion 155 is 10 journaled on a stud which projects upwardly from the slide 157. This slide is seated so as to be movable endwise in guide-ways 158 and such movement takes place in a direction which is substantially perpendicular to the direction of symmetrical relative movement of the clamping jaws 148, 149 in their guide-ways. The slide 157 is 15 movable in this manner for the purpose of adjusting the heel breast stop-faces 151, 151 toward and from the heel back-stop 150 to 20 accommodate heels of different lengths, and this movement of the slide 157 may be effected by means of an adjusting screw 160 (see Fig. 19). The guide-ways 158 for the 25 slide 157 form part of a normally stationary bracket 162 which is rigid with and extends horizontally from a slide block 163 hereinafter described. The adjusting screw 160 threads into an ear 164 on the bracket 162, 30 and the end of said screw 160 bears against a lug 166 integral with the slide 157 which projects downwardly through a slot in the floor of the bracket 162. At the opposite end of the slide 157 from the adjusting 35 screw 160, said slide has a second lug 168 (also projecting downwardly through the slot in the floor of the bracket 162) to which is attached one end of a tractile spring 170, the other end of said spring being secured 40 to a pin on the stationary ear 164. This spring 170 holds the lug 166 constantly against the end of the adjusting screw 160 so that when said screw is turned to move it endwise in the stationary bracket 162, its 45 movement in one direction pushes the slide positively with it and in the other direction permits the tractile spring 170 to draw the slide in the opposite direction. It will be noted that while the clamping jaws 148 149 50 are prevented from moving toward the heel back-stop 150 by the positive engagement of the adjusting screw 160 and the ear 164, said clamping jaws are nevertheless free to move in a direction away from the heel back-stop 55 150 though this movement is impeded by the tension of the tractile spring 170. This provision is of importance for reasons presently to be disclosed. When the heel carrier 60 is properly assembled on the machine, (see Fig. 2), the adjusting screw 160 is readily accessible to the boy standing at the rear of the machine.

Referring again to Fig. 15, the slide 157 has a projecting arm 172 at the end of 65 which, at 173, is pivoted a clamping jaw

adjusting lever 174. At one end said adjusting lever has an upwardly projecting pin 176 arranged to enter an aperture in the arm of the clamping jaw 149 (see Figs. 15 and 19) said aperture being sufficiently 70 elongated to permit a slight amount of play of the pin 176. Thus, when the clamping jaw adjusting lever 174 is rocked on its pivot 173, the clamping jaw 149 is given endwise movement; and this movement, 75 communicated through the pinion 155 to the other clamping jaw 148, causes the latter to move endwise in the opposite direction. Near the opposite end of the adjusting lever 174 from the pin 176, is attached a tractile 80 spring 178, its other end being secured to a lug projecting from the slide block 163. This tractile spring 178 tends constantly to rock the adjusting lever and move the side gripping faces 152, 152 of the clamping 85 jaws toward each other, so that a heel in the carrier is held yieldingly between said side gripping faces. The tendency of the spring 178, is opposed, for separating the side gripping faces 152, 152, and for determining their positions of nearest approach to each other, by means of an adjusting screw 180 threaded into the end of the lever 174 and arranged to abut against a rigid stop 182 projecting from the slide-block 163. When the adjusting screw 180 90 is turned in one direction it serves to separate the side gripping faces 152, 152; and when turned in the other direction it permits the tractile spring 178 to draw the 100 side gripping faces toward each other. Ordinarily, it is preferred to set the adjusting screw 180 so that the side gripping faces 152, 152 shall be spaced apart slightly less than the breast width of the heel intended to 105 be engaged. Thus, when the heel is introduced by the boy he can slightly separate the side gripping faces and then permit them (under the influence of the spring 178) to return sufficiently far to clamp the heel 110 yieldingly between them.

Referring to Figs. 15, 17, and 19, the heel back-stop 150 consists of an arm projecting laterally from a slide 184 which is arranged to move endwise (*i. e.* perpendicularly to 115 the acting face of the heel back-stop 150) in dovetailed guide-ways 186 supplied by the bracket 162. At one end the slide 184 has a downwardly projecting ear, 188, into which is screwed a heel back-stop adjusting screw 120 190. The cylindrical milled head of the adjusting screw 190 projects into an appropriately formed slot 192 in a projecting portion of the stationary bracket 162. With this arrangement the adjusting screw 190 is 125 precluded from bodily endwise movement so that when said screw is turned the heel back-stop slide 184 is adjusted back and forth substantially perpendicularly to its acting face, *i. e.* toward and from the rear of the 130

heel engaged thereby. Ordinarily, it is preferred that the boy set the adjusting screw 160 so that the heel breast stop faces 151, 151 shall be spaced from the heel back-stop 150 a slightly less distance than the length of the heel intended to be engaged, thus permitting the boy to push the heel against the breast-stop faces 151, 151 of the clamping jaws and to move them slightly away from the heel back-stop 150 against the tension of the spring 170. When the heel is finally located with its rear portion against the acting face of the heel back-stop 150 it will be held in this position by the tension of said spring 170. If, under these circumstances, the heel back-stop adjusting screw 190 be moved in such manner as to move the heel back-stop toward the heel, the movement of the back-stop will be communicated through the heel itself to the clamping jaws 148, 149 and the latter will be moved bodily with their slide, in consonance with the movement of the heel back-stop, against the tension of the tractile spring 170. When the heel carrier is properly assembled with the machine, (see Fig. 1) the heel back-stop adjusting screw 190 is readily accessible to the operator on the front of the machine and hence, with the arrangement just suggested, the operator, upon whom devolves the duty of properly assembling the heel with the heel seat of the shoe, is permitted readily to adjust the heel bodily back and forth lengthwise of the shoe by simply turning the screw 190.

To summarize: The boy at the rear of the machine, since it devolves upon him to arrange the heel properly in the carrier, is enabled, (see Fig. 2) by turning the adjusting screw 180, to adjust the clamping jaws to suit different widths of heel; and by turning the adjusting screw 160, to adjust the clamping jaws toward and from the heel back-stop to suit heels of different lengths. The operator, upon whom devolves the duty of positioning the heel with relation to the shoe, is enabled, by turning the heel back-stop adjusting screw 190, to move the heel bodily forward and backward until it registers with the heel seat of the shoe. Thus the operator and the boy each has convenient means for effecting the adjustments which pertain particularly to his part of the work.

Referring to Figs. 1, 2 and 5, when the heel carrier is in position on the machine the clamping jaws 148 and 149 and the heel back-stop 150 are so disposed as to hold the heel in a substantially horizontal plane and the various adjusting movements of the jaws and back-stop preferably take place in a horizontal direction. The top of the heel carrier (see Fig. 15) lies adjacent to the horizontal under face of a top tie-piece 194 which is stationarily supported between the uprights E E of the machine frame. This

under face of the tie piece serves to hold the clamping jaws 148 149 and the pinion 155 properly seated on the slide 157 and to maintain said slide in its proper position between the guide-ways 158. The nail block 7e H (see Fig. 5) is rigidly supported in the top tie-piece 194; and the lower face of said nail block overlies the clamping jaws 148 149, and the heel back stop, providing a rigid abutment for the top of the heel when the latter is positioned between the clamping jaws and back stop. 75

The top tie-piece 194 is preferably so constructed as to avoid interfering with the view which either the operator or the boy 80 has of the heel and toplift carriers and the work supported therein, and to facilitate inspection of the progress of the various operations on the shoe, the heel and toplift. To this end that portion of the tie piece which 85 overlies the carriers is made as narrow as practicable from front to rear of the machine; and, in fact, the width of the face adjacent the carriers is the least dimension of the tie piece used on the specific illustrative 90 machine. A convenient method of effecting this general purpose is to make the tie piece tapering, in cross section, toward the carriers as shown in Figs. 22 and 31.

On viewing Figs. 3, 4, 31, 32, 40 and 41, 95 it will be seen that the top tie piece 194 is in the form of a hollow head being so formed by reason of the provision of longitudinally arranged front and rear ribs 194^a and 194^b, and transversely arranged tie pieces 194^c. 100 As thus constructed, the head is open at the top and forms a recess for the reception of the awls G and drivers K. It will be noted that such a form of head provides a shield for the protection of the operator, and other 105 workmen whose duty brings them to the machine, as the ribs 194^a and 194^b extend upwardly adjacent the path of movement of the awls and drivers, and such moving parts operate within the vertical limits of the ribs. 110 Each of the ribs 194^a and 194^b, therefore, acts as a guard or shield to eliminate danger of injury to those who are working at the machine.

Referring to Figs. 15 and 18 the bracket 115 162 which supports the various parts of the heel carrier, has preferably integral with it the slide block 163 disposed parallel to the rear face of the top tie piece 194. This slide block 163 is arranged to travel back and forth across the rear of the machine upon a stationary track 198. The track 198 is affixed to the rear face of the top tie piece 194 by means of screws 200 which have their heads countersunk in the track 198 so as to 120 give the latter a smooth exterior. As shown in Fig. 22 (illustrating a like arrangement of a toplift slide block 204) the slide block and the track 198 are dovetailed together with a sliding fit and in this manner the heel 125 130

carrier is permitted to travel back and forth crosswise of the machine; in one direction to give place to a toplift which is carried into position beneath the nail block H, and 5 in the opposite direction to return the heel carrier to register with the nail block preparatory to inserting the next heel. It is preferred that the heel carrier move with the toplift carrier, and to this end the slide block 10 163 for the heel carrier, is conveniently tied by means of a rigid bar 202 to a slide block 204 of the toplift carrier (see Figs. 18 and 19).

Referring to Figs. 15, 18, 19, 20, 21 and 15 22 the toplift carrier J comprises toplift clamping jaws 206 and 207; a toplift back-stop 208, and a spanker plate 209. These are conveniently supported on a bracket 224 integral with the toplift slide block 204. 20 The clamping jaws 206, 207 have toplift breast stop faces 210, 210 and toplift side gripping faces 211, 211 which, as shown in the drawings, are substantially like corresponding parts of the heel carrier. The 25 clamping jaws 206, 207 are provided with rectilinear racks 212 which engage the teeth of an idle pinion 213 pivoted on a stud on the slide 214. The clamping jaw 207 is connected by means of a pivot pin 216 to a toplift clamping jaw adjusting lever 218 fulcrumed at 220 to a projecting arm of the slide 214. The other end of the lever 218 has secured to it a tractile spring 222 which acts between said lever and a rigid stud on 30 the toplift slide block 204. The tendency of this tractile spring 222 is to rock the lever so as to move the toplift clamping jaws 206, 207 toward each other for gripping a toplift 35 yieldingly between the side gripping faces 211, 211; and this tendency may be opposed for adjusting the clamping jaws by means of an adjusting screw 226 which is similar in all respects to the heel clamping jaw adjusting screw 180 and which normally abuts 40 against a rigid stop 228 on the slide block 204. Ordinarily, it is preferred that the adjusting screw 226 be so turned that the side gripping faces 211, 211 shall be spaced apart a less distance than the width of toplift 45 intended to be engaged between them, thus permitting the boy to introduce the toplift by moving the clamping jaws slightly apart and then raising the breast edge of the toplift between them, whereupon the side gripping faces seize the toplift in a yielding grip.

Referring to Figs. 15 and 20 the toplift clamping jaw slide 214, is mounted in ways in the bracket 224, and is adjustable endwise 60 therein by means of an adjusting screw 230 in the same manner as described in connection with the adjusting screw 160 of the heel clamping jaw slide 157. A tractile spring 232 (exactly similar to the spring 170 of the 65 heel carrier) is secured at one end to the

slide 214 and at the other end to a pin on the ear in which is threaded the adjusting screw 230.

Referring to Figs. 19, 20 and 22 the toplift back stop 208 is conveniently integral with 70 a toplift back stop slide 234, movable endwise in dovetailed ways 236 by means of an adjusting screw 238, in exactly the same manner as that already described in connection with the heel back stop.

In the particulars just described, the heel carrier F and toplift carrier J may be exactly alike, except that they are preferably arranged with the two sets of clamping-jaws and back-stops adjacent to each other to 80 permit a heel and toplift to be positioned conveniently near together so as to avoid the necessity for extended movement of the carriers in replacing a heel by a toplift, and in returning the heel carrier to its initial 85 position.

The toplift carrier is provided with a spanker plate 209. When a heel is in position in the heel carrier, it is desirable that the outer face of the heel be positioned proximate to the under face of the nail block, and that nothing intervene between said under face of the nail block and the heel to prevent nails from descending through holes in the nail block and entering the heel under 90 the influence of drivers. In the toplift spanking operation, however, it is preferable that a smooth imperforate surface be presented to the finished face of the toplift, in order to provide against disfiguring said 95 face when the pressure necessary for the spanking operation is exerted upon it. To this end it is considered expedient to insert a smooth imperforate spanker plate between the nail block and the toplift. In the specific devices shown in the drawings the spanker plate 209 is connected to the toplift carrier, moves with said carrier, and is constantly associated with the toplift gripping 100 jaws and toplift back-stop, so that it supplies always a smooth face against which the boy places the toplift when he inserts it, and against which the toplift is held preparatory to and during the spanking operation, performing in this latter respect an 105 office similar to that of the nail block in connection with the heel clamping jaws and heel back stop. When the toplift carrier is in its proper position on the machine the spanker plate 209 lies against the under faces 110 of the top tie piece 194 and the nail block H, which collectively supply a rigid abutment to sustain from above the spanking pressure 115 exerted from beneath.

The toplift back-stop adjusting-screw 238 125 is readily accessible to the operator who, by turning it, may adjust the toplift bodily back and forth in the same manner and to the same purpose that he adjusts the heel bodily by means of the heel back stop adjusting screw 130

190. It is desirable that provision be made for adjusting the spanker plate back and forth, in order that it may be positioned properly with respect to the toplift in whatever position the latter may be; and to this end the spanker plate 209 is mounted upon a slide 240 (see Figs. 15 and 20) which rests upon the toplift clamping jaw slide 214 and is guided by the same ways as the slide 214.
- 10 A spanker plate adjusting screw 242 is threaded into a portion of the toplift carrier slide block 204 and the milled head of said screw projects into an appropriately formed slot 244 in the slide 240. With this arrangement rotation of the screw 242 effects endwise adjustment of the spanker plate 209.
- To summarize: the boy at the rear of the machine, since it devolves upon him to arrange the toplift properly in the carrier, is enabled, by turning the adjusting screw 226 to adjust the toplift clamping jaws to suit different widths of toplifts; by turning the adjusting screw 230 to adjust the toplift clamping jaws toward and from the toplift back stop to suit toplifts of different lengths; and by turning the adjusting screw 242 to adjust the spanker plate back and forth in order to position it properly with respect to a toplift held by the clamping jaws and back stop. The operator at the front of the machine, upon whom it devolves to position the toplift properly for attachment, is enabled, by turning the toplift back stop adjusting screw 238 to adjust the toplift bodily forward and backward into registration with the heel previously attached to the shoe.

As already suggested the toplift carrier bracket 224 may be integral with the slide block 204, which is tied by means of the rigid bar 202 to the heel carrier slide block 163. The toplift carrier slide block 204 is (similarly to the heel carrier slide block) dovetailed with a sliding fit on the track 198.

Referring to Figs. 2, 15 and 18: projecting from the toplift carrier slide block 204 is a rigid stud 246, upon which is loosely journaled a block 248. The block 248 is embraced between bifurcations at the upper end of a toplift shifting lever 250. This toplift shifting lever 250 is fulcrumed at 252 to an actuating lever 254, which in turn is fulcrumed to a stud 256 rigidly supported in the frame of the machine. The toplift shifting lever 250 is connected at its lower extremity to the actuating lever 254 by means of a tractile spring 258 secured at its opposite ends to studs projecting from the respective levers. This spring holds the lower end of the toplift shifting lever 250 normally against an adjustable stop screw 260 threaded into an ear projecting from the actuating lever 254 (see Fig. 2). In this manner the toplift shifting lever 250 is permitted to yield in one direction and while moving in the other direction said lever 250 is to all in-

tents and purposes rigid with the actuating lever 254, so that the throw of the latter in one direction positively throws the former.

Referring again to Fig. 2, the lower end of the actuating lever 254 carries a cam 70 roll 262, which contacts with the toplift shifting cam 264 on the auxiliary shaft C. This cam 264 is a path cam which, with the auxiliary shaft C, has one complete revolution during the three cycles of the machine's 75 operation. This cam throws the toplift into spanking position after the heel has been nailed; and later returns the heel carrier after the toplift has been spanked on. The time relation of these operations to the 80 other operations of the machine will be explained later in connection with a detailed account of nailing and spanking.

The cam 264 moves the heel and toplift carriers F and J for bringing the toplift 85 into spanking position by a positive throw, and the extent of this throw may be adjusted by turning the stop screw 260 on the actuating lever 254; thus said screw serves as an adjustable stop permitting the final position 90 in which the toplift is presented to be accurately determined. When the cam 264 moves the heel and toplift carriers in the opposite direction (to the left, Fig. 2), a portion of the toplift carrier slide block 204 95 strikes against an adjustable stop 266, threaded into an ear projecting from the frame of the machine. When the slide block 204 abuts against the stop screw 266, the movement of the heel and toplift carriers is definitely arrested and further movement of the actuating lever 254 acts merely to distend the tractile spring 258 without being effective further to move the heel and toplift carrier. Thus, by means of the stop 100 screw 266, the return travel of the heel and toplift carriers for bringing the heel carrier 105 into its normal heel receiving position, may be accurately determined. As already explained, the heel carrier holds a heel in position against the under face of the nail block H preparatory to the pricking operation.

Referring to Figs. 1 and 5 the form of nail block preferred to be used in connection with the machine shown in the drawings 115 consists of a removable block H, supported in the top tie-piece 194, by means of a species of tongue and groove joint. To receive the nail block the top tie-piece 194 has a centrally located recess 268 (see Fig. 120 5) extending from the front of the machine rearwardly. The rear of the recess is semi-cylindrical. The lateral walls of the recess are provided throughout their extent with a horizontal groove 270, (Fig. 26) which 125 receives a correspondingly shaped tongue on the nail block H.

The nail block is best shown in Figs. 23 and 24. For convenience of manufacture it may be formed in three layers superposed 130

one upon another (see Fig. 24) the middle layer being arranged to project uniformly a slight distance beyond the other two layers to supply a tongue 272, which fits within 5 the groove 270 of the nail block recess 268 (Figs. 5 and 26). The rear portion of each layer of the nail block is made semi-cylindrical to conform to the shape of the recess.

A heel and a toplift lie alternatively beneath 10 the nail block, and to facilitate observation of the former, said block is made as narrow as practicable from front to rear of the machine. This is conveniently effected by making the lowest layer, or the two 15 lower layers, of the nail block narrower than the top layer as shown in Fig. 24, it being preferred to give the latter a considerable breadth to secure the additional support afforded thereby. When in its proper position 20 on the machine the curved rear of the nail block is firmly seated against the correspondingly shaped rear wall of the recess 268 and the tongue 272 of the nail block, throughout its entire extent is engaged by 25 the groove 270 of the recess 268. The nail block is introduced to the recess from the front of the machine by placing the tongue in position to register with the groove and moving the nail block rearwardly until its 30 rear face abuts against the back of the recess.

In order to prevent the nail block from being displaced from its proper position, a locking device is supplied which, when in locking 35 position, projects a latch into an angular notch 274 in the tongue 272 of the nail block. A convenient form of locking device is shown in Figs. 1, 25, 26, and 40. In the top tie-piece 194, at one side of the nail 40 block recess 268, is a partly-cylindrical recess 276 (see Fig. 40) which opens laterally into the groove 270. In this recess is located a parti-cylindrical block 278 (see Figs. 25 and 26) having for a portion of its lateral 45 surface a plane face, which when the block 278 is in proper position, constitutes a part of the inner wall of the groove 270 in the nail block recess. A lock shaft 280 is journaled in the block 278, and said shaft is provided at its outer end with an appropriate 50 handle 282. The inner end of the lock shaft 280 is preferably journaled also in bearings formed in the top tie-piece adjacent to the recess 276 (see Fig. 25). Between the inner 55 extremity of the block 278 and the rear wall of the recess 276 (see Figs. 25 and 40) is positioned an eccentric latch 284, rigid with the lock shaft 280, the periphery of 60 which is tapered to correspond in shape to the angular notch 274 in the nail block tongue 272. When all of the parts just described are assembled, the lock shaft 280 is incapable of axial movement, and the latch 284 is properly located to register with the 65 notch 274 in the nail block, the latter being

then in its rearmost position in the recess 268. Under these circumstances, the handle 282 is turned by the operator and thereby the eccentric latch 284 is rotated from a position of retirement in the recess 276 70 (shown by dotted lines, Fig. 25) until a portion of its periphery projects into and firmly engages the notch 274. The latch, remaining in this position until it is desired to remove the nail block, serves to hold the 75 latter securely in position against endwise movement; and therefore, by reason of the firm support of the nail block by the tongue and groove joint described, the nail block is rigid with the stationary top tie-piece 80 194, and affords an immovable abutment against which the heel may be held during successive operations of the machine when pressure is applied to the heel from beneath.

Referring to Figs. 23 and 24 the nail 85 block is supplied with a series of holes 286, which serve the purposes of permitting the awls to pass through the block from above to prick the heel (see Fig. 31); to receive the nails and position them preparatory to their 90 being driven into the heel; and to permit the nail drivers to pass downwardly and force the nails into the heel (Fig. 32). The disposition of the holes 286, 286 in the nail block, depends upon the number and arrangement of nails desired to be driven into 95 a heel, and since the number and arrangement of nails are likely to vary with different sizes and styles of heels, it is desirable for this reason to provide, as already described, for the removal of the nail block, so that it may be replaced by another having differently disposed holes.

In order that the proper positioning of the heel preparatory to the pricking operation 100 may be fully comprehended, it is expedient at this point, to describe the construction and mode of operation of the heel anvil I.

Referring to Figs. 30 and 37 the heel 110 anvil I consists preferably of a block approximating in the outline of its top surface, the shape of a heel seat. The top surface of the anvil is curved convexly in order that it may press against the concaved inner face 115 of a heel without distorting it; and in fact it furnishes a convenient means for giving desired shape to the heel face.

As shown in section in Fig. 30, the anvil has a downwardly projecting sleeve 120 embracing the upper end of a heel anvil stem 288 and a set screw in said sleeve secures the anvil I rigidly to said stem 288. Beneath the sleeve of the anvil the stem 288 is screw threaded in a milled adjusting nut 290. The stem 288 projects downwardly into an anvil supporting column 292, said column being provided with a through-pin 294, which projects into the interior of the column and engages a key-way in the stem 288, 130

to prevent rotation of the anvil. A pin 296 projects eccentrically through the anvil supporting column 292 and engages an annular groove on a portion of the adjusting nut 290 which projects into the column 292. This pin 296, while it prevents the adjusting nut 290 from being withdrawn from the supporting column 292, permits the nut to be turned freely and when so turned said nut 10 adjusts the heel anvil I vertically. The anvil supporting column 292 is rigid with a dovetailed slide 298, resting on the top of a heel anvil table 300, upon which the slide 298 is arranged to be moved back and forth 15 from front to rear of the machine in guideways 302, (see Fig. 5) which are dovetailed to engage the slide 298. This endwise movement (from front to rear of the machine) of the heel anvil slide 298 on the heel anvil 20 table 300, serves merely to withdraw the heel anvil from its active position to make place for the shoe jack and thereafter to return the anvil, and this will be more fittingly considered in connection with those operations 25 which take place preparatory to the second cycle.

The first step preliminary to the pricking operation is the introduction of the heel (and incidentally the toplift) by the boy. 30 At this time the heel anvil I stands directly beneath the heel carrier as shown in Fig. 30. It is one of the functions of the specific mechanism about to be described, to move the heel anvil I vertically upward until it 35 contacts with the heel; subsequently, when desired, to hold the heel firmly against the under face of the nail block while awls, hereinafter to be described, descend and prick holes in the heel.

40 Referring to Fig. 30, the mechanism for the purposes just suggested comprises a main jack spindle 304 carrying the heel anvil table 300 at its upper extremity; a sleeve 305 encircling the spindle 304; a jack lifting frame 306; and a jack actuating cam 308. The heel anvil table 300 has a dovetailed groove on its under face, extending crosswise of the machine, which receives a dovetailed tongue 307 of a cap block 309 secured by a set screw on the upper end of the spindle 304. This tongue and groove have a sliding fit, permitting the table 300 with the heel jack I to be adjusted crosswise of the machine as hereinafter described in 50 connection with similar adjustment of the shoe jack. The main jack spindle 304 is screw threaded near its upper extremity to engage an adjusting nut 310; and extends therefrom downwardly into the spindle sleeve 305. This sleeve 305 is enlarged at its top to provide a vertical bearing for the adjusting nut 310; and a key 311 in the sleeve 305 projects into an annular key-way on the adjusting nut, to prevent the latter from 55 being withdrawn from the sleeve and to

allow the nut free rotation therein. Thus if the adjusting nut 310 be rotated, the spindle 304 will be adjusted axially in the sleeve 305. The nut 310 is rotated to this end through gear teeth 312 on its periphery, by means which may be more pertinently discussed in connection with a shoe jack adjusting mechanism of which the nut 310 forms a part. It will suffice to say here that if the nut 310 be prevented from rotating (and it is so prevented, ordinarily, during the pricking operation) the spindle 304 and the spindle sleeve 305 are in effect rigid with each other so that movement of the latter moves also the former. For the purposes of this immediate discussion, then, the spindle 304 and sleeve 305 may be considered as relatively rigid.

During the first cycle, the main jack spindle 304 is yieldingly elevated until the heel anvil abuts and rests against the heel, and shortly thereafter said spindle is positively elevated through a predetermined limited distance, in order to compress the heel 85 slightly by means of the heel anvil I, the pressure exerted by the latter upon the heel from below being sustained from above by the under face of the nail block H. The jack actuating cam 308 acts directly upon 90 the jack lifting frame 306 and such positive movement as is automatically given to the main jack spindle 304 by the mechanism of this specific machine is communicated to it from this jack lifting frame 306, the 95 sleeve 305 and the frame 306 being locked together for this purpose so that to all intents and purposes said sleeve, spindle and frame are rendered temporarily rigid with 100 each other and the action of the jack actuating cam 308 is transmitted directly to the main jack spindle. Except through the intermediation of the jack lifting frame 306, the main jack spindle is never acted upon 105 positively by the jack actuating cam 308. 110 The yielding elevation of the main jack spindle 304 is effected by means of a compression spring 313 which is interposed between a portion of the sleeve 305 and a portion of the jack lifting frame 306, positive elevation of the latter by the cam 308 serving to compress said spring which, after reaching a certain degree of compression, elevates the sleeve 305, the main jack spindle 304, and the heel anvil I carried thereby until the latter abuts and rests against heel. Shortly after the heel anvil abuts against the heel the sleeve 305 is locked in rigid association with the positively actuated jack lifting frame 306, continued movement 115 of which positively presses the heel anvil against the heel. The jack spindle sleeve 305 is mounted so as to be vertically movable in bearings in a central tie piece 316 supported between the uprights E, E of 120 125 130

the machine frame, (Fig. 5) the sleeve 305 projecting downwardly through these bearings and into and through a closed chamber formed by the jack lifting frame 306. The 5 downward movement of the sleeve 305 in its bearings is limited by a shoulder 314 on the outside of the sleeve abutting on an internal shoulder of the bearings (see Fig. 30).

- 10 Referring again to Fig. 30, a sleeve having a lug 318 is rigidly pinned to the spindle sleeve 305, the lug 318 projecting therefrom into a slot 320 (see Fig. 2) in the central tie piece, the engagement between the lug 15 318 and said slot serving to prevent rotation of the sleeve 305 while permitting said sleeve freely to reciprocate vertically in its bearings. Said lug 318 supplies also an abutment for the upper end of the compression 20 spring 313 already referred to, by means of which the main jack spindle is given its yielding elevation. As shown in Fig. 33 the lower end of said spring abuts against an ear 322 on the jack lifting frame 306. Preferably, as shown in Fig. 33, the lug 318 has an adjusting screw 321 for varying the tension of the spring 313, the top of said spring bearing against an annular collar on the head of the screw 321.
- 30 Referring to Figs. 5, 30, 33, 35 and 36, the jack lifting frame 306 consists of an oblong, box-like structure disposed cross-wise of the machine and having projecting tongues 324 arranged to be vertically movable in guide- 35 ways 326, 326 fixed respectively upon the inside of the uprights E E of the machine frame. The entire structure of the jack lifting frame 306 is vertically reciprocated by the jack actuating cam 308. Projecting 40 downwardly from the base of the jack lifting frame 306 is a yoke 328 (see Figs. 1 and 30) which straddles a block 330, (Fig. 5) mounted upon the main shaft B. Preferably the block 330 is formed in two parts, 45 which embrace the main shaft between them and are held in position by the arms of the yoke 328. This permits the block 330 to be removed readily, when desired, by simply withdrawing the yoke 328 so as to disengage 50 the parts of the block, thus avoiding any necessity for removing the main shaft from its bearings. At the top of the yoke 328 (see Figs. 5 and 30) the jack lifting frame 306 carries a cam roll 332, which projects 55 laterally into a cam path 334, provided by a cam wheel 336. Thus, rotation of the main shaft reciprocates the jack lifting frame 306 vertically, the cam path being arranged to move said frame positively in both directions.

60 Referring to a diagrammatic representation of this cam in Fig. 30, the position of the cam roll 332 when the machine is at rest before the first cycle, is there shown. The

cam path 334 moves in the direction indicated by the arrow in the figure just referred to. During this movement of the cam, the cam roll 332 encounters in succession a rise 340, a short dwell 341, a second rise 342, a dwell 344, and a down track 346, resuming 70 its initial position upon a dwell 348. During the second half revolution, the cam roll 332 encounters in succession a rise 350 (exactly like the first rise 340), another short dwell 351, a second rise 352 (exactly like the 75 rise 342), a dwell 354 (considerably shorter than the corresponding dwell 344), a down track 356, and its original dwell 358. The cam roll 332 rests upon the dwell 358 when the first cycle ceases at the end of one revolution of the main shaft. Evidently, then, the specific cam path designed as just described acts during each complete revolution of the main shaft first, to elevate the jack lifting frame 306 through one step and to 80 rest for a moment; second, to complete its elevation by another step; third, to return the jack lifting frame downwardly to its initial position; fourth, again to elevate the jack lifting frame through one step and to 85 rest a moment; fifth, to elevate said frame further through another step; and, sixth, to return the said frame downwardly to its original initial position which it occupies at the end of the revolution of the main 90 shaft when the machine is brought to rest by the stop motion at the end of the first cycle. This particular partition of the travel of the jack lifting frame 306 is not essential to the present invention but it is 100 found to be convenient in connection with the specific machine which is the subject of the present detailed description.

As regards the first cycle (the pricking operation), the jack lifting frame 306 during its elevation by the cam rise 340 compresses the spring 313, and therethrough moves the sleeve 305 and the main jack spindle 304 yielding upward until the heel anvil I abuts against the heel. When the jack lifting frame 306 rests for a moment after its first step of elevation, said frame and the spindle sleeve 305 are locked together so that said second step moves the heel anvil I positively upward to grip the heel tightly between the latter and the nail block H. The jack lifting frame and spindle continue locked together for a time during which the dwell 344 of the cam path serves to keep the parts at their extreme elevation long enough for the pricking awls to descend and prick the nail holes in the heel. After the pricking operation, the down-track 346 of the cam path 334 permits the jack lifting frame to descend and before this descent the spindle sleeve 305 is unlocked from the jack lifting frame 306. As the latter descends, the spring 313 is relieved from its recent

compression and the jack spindle 304 is permitted to return downwardly to its initial position by its own weight. Thus, the main jack spindle and the jack lifting frame re-

sume their original positions when the pricking operation has been completed, and at the end of one-half a revolution of the main shaft. During the next half revolution of the main shaft, to complete the first cycle, the heel anvil I is again, but idly, yieldingly and then positively elevated and later depressed by the cam tracks 350, 352 and 356. During the third cycle the action of the cam tracks just enumerated becomes again effective to elevate the shoe jack as hereinafter explained for the top lift spanking operation.

The manner in which the jack spindle sleeve 305 and the jack lifting frame 306 are locked together for positively moving the former will be next described.

Referring to Figs. 30, 35 and 36, the jack spindle sleeve 305 extends downwardly through bearings 359 in the top wall 360 and similar bearings in the bottom wall 361 of the box-like structure constituting the jack lifting frame 306. The lower portion of the jack spindle sleeve positioned thus within the said top and bottom walls is coarsely screw-threaded and is encircled by a jack spindle locking nut 363. The lower portion of the nut 363 is reduced to form a cylindrical hub 364 which fits easily in bearings provided in the bottom wall 361 of the jack lifting frame (see Fig. 36); and the main body of the nut, above said hub 364 supplies an annular shoulder 365 which seats upon the bottom wall 361. The height of the nut 363 above the shoulder 365 is such that the nut fits easily between the top bearings 359 and the bottom wall 361 of the jack lifting frame. In this manner the nut is confined within the box-like structure of the jack lifting frame and is compelled to partake of the vertical movement of the latter, while at the same time it is normally free to rotate therein about the jack spindle sleeve 305. As already explained, the jack spindle sleeve 305 is prevented from rotating by a lug 318 rigid with the sleeve which is confined against lateral movement in the slot 320 of the stationary central tie piece 316. Thus, relative vertical movement of the jack lifting frame 306 and the spindle 305 is necessarily accompanied by rotation of the locking nut caused by the screw threads on the non-rotatable spindle sleeve. That is to say, if said locking nut be prevented from rotating, relative movement of the jack lifting frame 306 and the main jack spindle 304 will be impossible and a positive movement of the former will be transmitted positively through the locking nut 363 to the latter. It is convenient therefore, to arrest

the rotation of the jack spindle locking nut 363 during the required time, in order to cause the heel anvil I to exert positive pressure against the heel.

Referring to Figs. 35 and 36, the cylindrical outer wall of the locking nut 363 is provided with a series of vertical ratchet teeth 366. Two pawls 368 and 369 are mounted one above the other on a vertical stud 370 supported in a hub 371 integral with the top wall 360 of the jack lifting frame 306. Under proper circumstances one or the other of these pawls stands in position to engage a peripheral tooth 366 of the jack spindle locking nut 363; and, preferably, the stud 370 is so located that any thrust upon the point of the pawl by the ratchet teeth of the locking nut will be transmitted to said stud tangentially to the locking nut 363, thus providing that lateral strain on the pawls shall be minimized.

It is considered expedient to make the ratchet teeth 366 on the locking nut 363 rather large and heavy in order that they shall be sufficiently stable to withstand the strain to which they are subjected; and in order that one or the other of the pawls shall be always in position to engage some one of the teeth 366 it is convenient to make one of the pawls somewhat longer than the other, the difference in length between the two pawls amounting to approximately one-half the distance between adjacent ratchet teeth 366. Thus, while one of the pawls may not be in position to engage a tooth 366 the other will be, and prompt co-action of the pawls and ratchet teeth is thereby insured.

Automatic means are provided for holding the pawls normally out of engagement with the ratchet teeth of the jack spindle locking nut 363, for permitting relative movement of the jack lifting frame 306 and the jack spindle sleeve 305; and provision is also made for automatically engaging the pawls and the ratchet teeth on the locking nut in order to lock together the jack lifting frame and jack spindle sleeve so that the latter may be positively elevated by the movement of the former. The mechanism for controlling the pawls to these ends will be next described.

Referring to Figs. 35 and 36, the pawl 368 has an integral arm 372; and the pawl 369 has an integral arm 373. These two arms on their adjacent faces carry, respectively, projecting lugs 374, 374 which register with each other end to end and together are engaged between the arms of a forked pawl controller bar 376 (see Figs. 33 and 35). The end of the bar 376 opposite to the fork which engages the lugs 374, 374 is pivoted by means of a pin 378 between the bifurcations of a pawl controlling lever 379 (see also Fig. 1). The pawl controlling

lever 379 is rigid with a shaft 380, journaled in ears 382, projecting from the front side of the jack lifting frame 306.

As shown in Fig. 33 each bifurcation of 5 the pawl controlling lever 379 is connected by means of a tractile spring 384 with an arm 372 or 373 of a pawl 368 or 369, said tractile springs 384, 384 serving to prevent the lugs 374, 374 escaping from the fork of 10 the pawl controller bar 376. Evidently, when the pawl controlling lever 379 is rocked in one direction it acts through the agency of the pawl controller bar 376 to rotate both of the pawls 368 and 369 out 15 of engagement with the jack spindle locking nut 363; and when the pawl controlling lever 379 is rocked in the opposite direction the tractile springs 384 act to throw the pawls yieldingly into engagement with the 20 jack spindle locking nut and thereby to arrest or prevent rotation of the latter. The pawl controlling lever 379 (rigid with its shaft 380) is rocked back and forth to the ends just suggested by means of a cam arm 25 386, also rigid with the shaft 380 (see Fig. 33), which is provided with a cam roll 388. The cam roll 388 is engaged periodically to rock the cam arm 386 and therethrough the pawl controlling lever 379, by means of cam 30 blocks 390, 391 carried on the cam wheel 336 of the main shaft B. The pin 378 (upon which the pawl controller bar 376 is pivoted) is extended downwardly (see Fig. 33) to provide a point of attachment for a tractile 35 spring 392, the other end of which is secured to a pin fixed in the bottom wall 361 of the jack lifting frame 306. This tractile spring 392 acts normally to hold the parts just described in the position shown in Figs. 40 35, in which the pawls 368 and 369 are removed from engagement with the ratchet teeth of the jack spindle locking nut 363. The pawls are held thus by the spring 392 until a locking cam block 390 or 391 rocks 45 the pawl controlling lever 379 against the influence of the spring and permits the springs 384 to throw one or the other of the pawls into engagement with a tooth on the jack spindle locking nut 363.

50 The co-action of the jack actuating cam 308 and the locking cam block 390 is such that the latter arrives in position to throw the pawl controlling lever 379 so as to permit the pawls to engage the locking nut 363 55 and arrest or prevent its rotation, when the cam roll 332 of the jack lifting frame 306 is in engagement with the short dwell 341 (see Fig. 30). That is to say, between the first step of elevation of the main jack spindle 60 304, and the beginning of its second step of elevation, the spindle sleeve 305 and the jack lifting frame 306 are locked together so that the positive movement of the latter is transmitted directly to the former with the result 65 that the heel anvil I is forced with positive

pressure against the heel. In the specific machine now under discussion, the jack lifting frame is reciprocated vertically in a path which is about one and one-fourth inches long. In moving from the lower- 70 most extremity of the path upwardly, the jack lifting frame 306 is carried about one and one-eighth inches by the first rise 340 of the jack actuating cam 308, and is thereupon locked to the jack spindle sleeve 305. 75 The latter, therefore, moves positively with the jack lifting frame 306 during the last one-eighth of an inch of the upward movement of said frame. As already explained, the heel anvil I is placed yieldingly against 80 the heel during the early upward movement of the jack lifting frame 306. During the later movement of said frame, the heel anvil I is moved positively upward one-eighth of an inch with the result that the heel is compressed approximately one-eighth 85 of an inch. It will be observed that whenever the heel anvil I is first arrested by abutting against the heel (regardless of the height of the heel) said anvil will be further 90 elevated through one-eighth of an inch before reaching the final upward limit of its movement. This insures that all heels, irrespective of variations in their heights, will be given a uniform compression of approximately 95 one-eighth of an inch. It is to be understood, of course, that these specific dimensions in connection with the steps of movement of the jack lifting frame and the main jack spindle are not essential to the 100 present invention. The compression of the heel in the manner just described, while desirable, does not contribute essentially to the pricking operation, it being sufficient if the heel is supported with enough security 105 to sustain the pressure exerted by the pricking awls about to be described. When the heel has been compressed (or if not compressed, properly secured in place beneath the nail block) the series of awls G (Fig. 110 31) is projected downwardly through the holes in the nail block H and is pressed into the heel to make holes for the reception of the nails.

115 It has been stated that it is frequently desirable to have heelng nails variously disposed for attaching different heels; and that it is desirable to have the holes in the nail block arranged to correspond to the disposition of nails required for a particular 120 heel. Obviously, it is important that the awls be positioned to register respectively with the holes in the nail block and in order that differently positioned series of awls 125 may be used from time to time on the machine each series is secured to an awl block 394, which is removable from the machine.

130 For the purposes of the specific machine under discussion, it is necessary that at one time the pricking awls be in a position to

register with the holes in the nail block; and that at another time nail drivers be in a position to register with said holes. In order to provide for the ready replacement 5 of the awls by the drivers, and vice versa, it is convenient to mount a series of awls and a series of drivers on a turret 396 and to provide automatic means for rotating said turret at proper times to present the awls 10 and drivers alternatively in active position.

Referring to Figs. 1 and 5, the awls G are mounted in the awl block 394, which is arranged to fit in a dovetailed seat in the turret 396. A portion of the dovetailed seat on 15 one side of the turret (see Fig. 5) is supplied by a clamping block 398, which is retained in place on the turret by a clamping screw 400. More or less remote from the dovetailed seat for the awl block, the clamping block 398 has a projecting shoulder 402, which serves as a fulcrum upon which the clamping block 398 may be moved by screwing in the clamping screw 400 so as to cause 20 the active clamping face of the block 398 to grip the awl block 394 and hold the same securely in place. An adjustable stop screw 404 threads into the front edge of the awl block 394 (see Fig. 1) and a part of the 25 head of the screw 404 projects beyond the awl block in position to abut against the turret when the former is pushed into place by moving it endwise in its dovetailed seat. Thus the stop screw 404 supplies adjustable 30 means for determining the position of the awl block in the turret.

Referring to Figs. 5 and 32, the turret 396 has a hub 406, rigid with a turret shaft 408. The shaft 408 is journaled in a bifurcated 40 bracket 410 (see Figs. 2 and 32) projecting 45 downwardly from the pricking and driving beam 412, the turret hub 406 lying between the bifurcations of the bracket 410. The turret shaft 408 extends from the front toward the back of the machine. On the front 50 extremity of said shaft (see Figs. 1 and 32) is rigidly secured a sector gear 414 which meshes with a rectilinear rack 416, arranged to slide endwise in ways 418; and the turret 396 is rocked or oscillated for replacing the awls by the drivers and vice versa by moving the rack 416 endwise in its ways.

As shown in Fig. 1, the rack 416 has at its right hand end a vertically elongated slot 419 into which projects a block 421 journaled upon a stud at the upper extremity of 55 a turret actuating lever 420. The elongation of the slot 419 accommodates the vertical reciprocation of the rack while preserving effective connection between the rack 60 and lever. The lever 420 is rigid with a pivot pin 422, which is journaled in the frame of the machine (see Fig. 1). Also rigid with the pivot pin 422 is a downwardly projecting arm 424, (see also Fig. 3) which in 65 effect forms an integral part of the turret

actuating lever 420. Loosely mounted on the pivot pin 422 is a cam lever 426, which communicates the action of a turret actuating cam 428 upon the auxiliary shaft C, to the lever 420. The arm 424 of the lever 420 70 is confined between two adjustable set screws 430, carried in ears on the cam lever 426. Evidently, if one of these screws be retracted slightly and the other be moved inwardly the relations of the cam lever 426 75 and the turret actuating lever 420 will be varied so as to adjust the limits of endwise movement of the rack 416. Thus the set screws 430 provide for adjusting the positions in which awls and drivers will be held 80 at the extreme throws of the turret actuating cam 428. The time relation of the turret actuating cam 428 and the other parts of the machine will be explained hereinafter. It is sufficient at the present time to say that 85 said cam presents the pricking awls in position to register with the holes in the nail block at the beginning of the first cycle.

As already suggested, the pricking and driving beam 412 is reciprocated vertically 90 for pricking the heel and later for driving the nails. To provide for this vertical reciprocation, the said beam is rigidly secured to the tops of two vertical pricking and driving plungers 432. These plungers are 95 preferably cylindrical and are supported in appropriate bearings in the tie-pieces of the machine. Referring to Figs. 1 and 5, in the vicinity of the main shaft B each of the plungers 432 has a top cam roll 434 and a 100 bottom cam roll 436. The top cam roll 434 (see Fig. 3) is engaged constantly by the topmost portion of a frog cam 438; and the bottom cam roll 436 is constantly engaged by the lowermost portion of a frog cam 440, 105 both of said cams being keyed to the main shaft B. The cams 438 and 440 are duplicated at opposite ends of the main shaft B for reciprocating the respective pricking and driving plungers 432. The arrangement of these cams 438 and 440 with relation to the cam rolls 434 and 436 is such that the plungers 432 are positively moved both upwardly and downwardly and both of said 110 rolls are preferably constantly engaged by 115 their respective cams.

Referring to a diagrammatic representation of one pair of these cams in Fig. 3, the direction of rotation of the cams is indicated by an arrow 442, and the positions of the cam rolls 434 and 436 at the beginning of the first cycle are indicated, with their appropriate reference characters, by broken line circles.

The cams 438 and 440 have the positions 125 shown in Fig. 3 at the time when the jack actuating cam 308 has the position shown in Fig. 30. It is expedient at this point to describe the correlation of these cams, in order that the time relations of the pricking 130

operation and the anvil elevating operation may be clearly understood. When the machine is at rest prior to the initiation of the first cycle the pricking and driving beam 412 stands at the uppermost limit of its movement, it having been elevated thereto by the cam 438 arriving in the position shown in Fig. 3. When the machine starts for the first cycle the cam 440 begins substantially at once to depress the cam roll 436, and thereby to move the pricking awls toward the nail block. At the end of a quarter-revolution (see arrow 442, Fig. 3), the pricking awls have been depressed to the full extent of their movement by the cam 440. The awls reach and penetrate the heel during the latter part of this quarter-revolution.

Referring now to Fig. 30: it will be observed that the first quarter-revolution of the jack actuating cam 308 serves to elevate the heel anvil I by means of the cam rises 340 and 342; and thereupon, during the latter part of this first quarter-revolution, the heel anvil is caused to dwell in its elevated position. Preferably, this dwell 344 becomes initially active a short time before the pricking awls, depressed by the cam 440, begin to penetrate the heel. During the second quarter-revolution of the cams 438 and 440, the pricking and driving beam 412 is again elevated to its highest position; and during the next succeeding half-revolution of these cams, (while the heel anvil is being idly reciprocated) the beam 412 dwells in its highest position, and there remains upon the completion of the cycle.

When the awls during their upward movement have been withdrawn from the holes in the nail block in the first cycle nails are delivered automatically to said holes and there rest until driven through the heel and into the heel seat during the second cycle.

As already stated the heel anvil I at the beginning of the first cycle stands directly beneath and registers with a heel in the heel carrier, having then the position shown in Fig. 30. As the heel anvil I moves downwardly after the completion of the pricking operation it is withdrawn toward the rear of the machine in order to make way for the shoe jack which, preparatory to the nailing operation receives the shoe to be heeled and then is pushed by the operator from the front into position beneath, and to register with, the pricked heel still held in the carrier. This removal of the heel anvil to make way for the shoe jack is effected by moving the heel anvil slide 298 rearwardly in guide-ways on the heel anvil table 300.

Referring to Figs. 33 and 37, for this purpose, the heel anvil slide 298 has integral with it a frame containing a vertically disposed slot 444. Within said slot 444 is mounted (see Fig. 33) a block 446, in which

is journaled a stud 445 fixed in the upper end of an anvil retracting lever 448. For purposes of adjustment the stud 445 (see Fig. 34) is eccentrically mounted upon a hub 447, said hub being seated in the upper end of the anvil retracting lever 448. The hub 447 has appropriate apertures to be engaged by a spanner wrench, by which the hub and its eccentric may be turned. This turning adjusts the heel anvil slide 298 back and forth in its guide-ways on the table 300 and adjusts the anvil with relation to the heel. The hub is locked in adjusted position by means of a set screw 449, (Fig. 32) at the top of the lever 448 (see Fig. 32) which passes through the split end of said lever and is arranged to close the split and thereby to clamp the hub 447. The anvil retracting lever 448 (Fig. 33) is fulcrumed at its lower extremity upon a stud 450, supported in a part of the bottom tie-piece of the machine frame. Near its middle portion said lever 448 carries a laterally projecting cam roll 451, which engages an anvil retracting path cam 453 on the auxiliary shaft C (see Fig. 33).

The relation between the anvil retracting cam 453 and the jack actuating cam 308 may be observed conveniently in Fig. 30, an arrow 455 indicating the direction of rotation of the cam 453 which is shown in the position it occupies just prior to the beginning of the first cycle. It should be borne in mind that the cam 453 on the auxiliary shaft C moves at one-half the speed of the cam 308 on the main shaft B.

During approximately the first sixty degrees of rotation of the anvil retracting cam 453, the cam roll 451 rides upon a dwell 457, the heel anvil I remaining unaffected. This first sixty degrees of rotation of the anvil retracting cam 453 is accompanied by substantially one hundred twenty degrees of rotation of the jack actuating cam 308 and consequently the dwell 457 is sufficiently long to allow the heel anvil (1) to be elevated to its extreme position by the cam rises 340 and 342, (2) to remain in this position under the influence of the cam dwell 344 and (3) to begin its downward movement with the down track 346 after the completion of the pricking operation. During a part of the downward movement of the heel anvil, however, the cam roll 451, encounters a retracting path 459, on the cam 453, which acts to rock the anvil retracting lever 448 from the position shown in Fig. 30 to the position shown in Fig. 32, thereby withdrawing the heel anvil from beneath the heel in its carrier to make way for the shoe jack. Upon leaving the retracting path 459, the cam roll 451 enters a dwell 461, whereby the heel anvil is held in its rearmost position, where it remains when the cam 453 has rotated through one hun-

dred eighty degrees and the first cycle is finished.

Referring to Fig. 1: the turret actuating cam 428 on the auxiliary shaft C is so disposed that the turret dwells in position with the pricking awls registering with the holes in the nail block, prior to the first cycle and during substantially the first half of the cycle while the awls are being depressed to 10 prick the heel and until they have been entirely withdrawn from the holes in the nail block. Thereafter, the turret actuating cam 428 rocks its lever 420 with the result that, at the end of the first cycle, the pricking awls have been replaced by drivers which then register with the holes in the nail block in position to drive the nails recently delivered to said holes.

The series of drivers K (of the same number and disposition as the pricking awls for reasons already discussed) are carried in a removable block 463 which is secured to the turret, for convenience, in exactly the same manner as the awl block 394. Also the 25 driver block 463 is provided with an adjustable stop screw 465 similar in all respects to the adjustable stop screw 404 of the awl block 394. Preferably the acting ends of the drivers are slightly concaved to permit them to engage the convex heads of the nails without slipping (see detail of a driver K, Fig. 29).

To summarize: Preparatory to the first cycle the boy at the rear of the machine introduces a heel and a toplift to their respective carriers, the heel being then positioned beneath the nail block H (Fig. 31). At this time the heel anvil I stands, in the position shown in Fig. 30, directly beneath the heel; and the awls registering with the holes in the nail block H stand above the nail block. When the boy depresses his treadle the machine is started for the first cycle. Thereupon the heel anvil is first yieldingly elevated until it abuts against the heel, and subsequently is positively elevated to hold (and also it may be to compress) the heel between itself and the nail block H. During this movement of the heel anvil the awls have descended through a part of their travel; and when the heel is finally gripped, the awls, passing through the holes in the nail block, prick the heel in the manner illustrated in Fig. 31. This having been done, the awls ascend while the heel anvil descends and is retracted from its position beneath the heel to the position shown in Fig. 32. After the heel anvil has been thus retracted, it is moved again vertically upward and then downward, but this movement, so far as the first cycle is concerned, is idle and need not be further discussed at this time. When the awls have been withdrawn from the holes in the nail block, nails are delivered automatically to said holes.

During the latter part of the cycle the turret is rotated to replace the awls by the drivers which then stand in position to register with the recently delivered nails. During this cycle a shoe jack L occupies the position shown in Fig. 30, and is unaffected by the various movements of other parts of the machine; and said jack L remains in the position shown in Fig. 30 until it is shoved back beneath the heel into alignment with the main jack spindle 304 (as indicated in Fig. 32) by the operator after the heel anvil I has been retracted. Thus the parts stand at the end of the first cycle; the jack actuating cam 308 having completed 75 one revolution and returned to the position shown in Fig. 30, the heel anvil retracting cam 453 having rotated through one hundred eighty degrees from the position shown in Fig. 30; and the pricking and nailing 80 beam actuating cams 438 and 440 (Fig. 3) having completed one revolution and returned to the positions shown in Fig. 3.

Preferably the period of activity of various parts of the machine during the first 90 cycle in no way interferes with the operator, who is engaged in jacking the shoe, *i. e.*, in arranging the shoe in proper position on the shoe holding means hereinafter described. The control of the machine during 95 the first cycle being entirely in the hands of the boy, the operator is permitted to make the necessary preparation without interruption until the first cycle comes to an end and the control of the machine is given over to 100 him.

On heelers machines of certain types known in the art, a shoe is mounted on an iron or steel last or jack adapted to withstand the sudden strains involved in the operation of such machines. Since a shoe is nearly always lasted and otherwise treated on a wooden last it is necessary, obviously, to remove such wooden last before placing the shoe on the iron jack of the machine; 105 and subsequently, it is important that the shoe be provided with a wooden "follower" last for the remaining shoe-making operations. It is desirable, however, to avoid, in so far as possible, insertions and substitutions of lasts because of the distortions and deformations of shoes that necessarily result therefrom; and consequently it is to be preferred that a heelers machine be capable of attaching heels, in practice, to shoes mounted 110 on their ordinary wooden lasts.

The specific machine which has been the subject of the preceding description is designed to supply the preference just explained, and also the preferred form of shoe 125 holding devices about to be described are especially adapted to hold shoes which are mounted on wooden lasts. As will appear hereinafter, the machine may be adapted for attaching heels from which the wooden last 130

has been removed and replaced by a steel jack or the like. For the present, however, it may be understood that the specific shoe holding means about to be described, are intended to be used in connection with wooden lasts.

Referring to Figs. 30, 31, 32, 33, 37, 38 and 39: the principal instrumentalities of the shoe holding means are a shoe jack L, cooperating counter clamps M, M, and a toe saddle N. These parts are shown in front elevation in assembled position on the machine in Fig. 1, and in rear elevation in Fig. 2.

As shown in Figs. 30 and 39, the shoe jack L has a last pin 467, intended to project into the usual steel-shod socket in a wooden last; and has also a curved lower face including a dovetailed tongue 468. Said tongue (see Fig. 39) seats in a similarly shaped groove in a jack block 470. The jack L is thus arranged to slide endwise (which is lengthwise of the shoe) in a curved path, in order to adapt the last pin 467 to any practicable oblique trend which may be desired to be given to a shoe, and to pitch the heel forwardly or backwardly as the style of the shoe may demand.

Preferably the curved lower face of the jack L and its similarly curved seat are constructed on the arc of a circle having its center at approximately the average center of the heel seats of shoes when positioned upon wooden lasts on the jack. With this arrangement effected as nearly as is practicable, considering varying heights of shoes and the like, shoes may be tilted to any usual degree without causing material variances in the elevation of their heel seats. While this specific construction of jack is considered convenient, it is by no means essential to shoe holding means embodying features of this invention.

The jack block 470 is secured by a through pin 471 (Fig. 33) to a cylindrical shank 472 (see Fig. 30) and this shank 472 projects downwardly into a jack supporting column 474. A portion of the shank 472 threads into a milled adjusting nut 476, similar to the adjusting nut 290 for the heel anvil. The nut 476 has a reduced portion which projects downwardly into the jack supporting column 474, and said reduced portion has a peripheral groove engaged by a pin 479 driven through the walls of the jack supporting column 474. This pin 479 prevents withdrawal of the nut 476 from the column 474, but at the same time permits the nut to be freely rotated. When the nut 60 is thus rotated the shank 472, and with it the jack L, is adjusted vertically relatively to the column 474.

Referring to Figs. 30 and 38: the jack supporting column 474 is preferably integral with a dovetailed slide 481 arranged

to slide endwise (from front to rear of the machine) in a dovetailed guideway in the jack supporting table 483. This jack supporting table, it should be understood, is separate from the anvil supporting table 300, as shown in Fig. 31 wherein the latter has been elevated independently of the former, although it is adapted for alinement therewith.

On its lower face (see Fig. 30) the jack table 483 has a dovetailed groove which is engaged by a dovetailed tongue 485 rigid with the top of a jack table adjusting screw 486. Thus the jack supporting table 483 is adjustable crosswise of the machine, the dovetailed grooves in the table sliding on the tongue 485.

As shown in Fig. 38 the jack table 483 has depending from its sides, rigid brackets 488, 488; and each of said brackets has threaded into it an adjusting screw 490. These screws 490, 490 are therefore normally rigid with the jack table 483. The adjacent ends of the screws 490, 490 abut against opposite sides of the dovetailed tongue 485 on the jack table adjusting screw 486; and hence, if one of said screws be loosened and the other screwed up, there will result a lateral adjustment (crosswise of the machine) of the jack table 483 on the tongue 485.

As shown in Fig. 37, each bracket 488 has a rearwardly extending projection 492; and these projections embrace snugly between them the front edge of the anvil supporting table 300. Hence, adjustment of the jack supporting table 483 by means of the adjusting screws 490, effects also a like lateral adjustment of the anvil supporting table 300. Since the latter is given considerable vertical movement independently of the jack 483, the anvil 300 is provided with rigid downwardly projecting guards 493 (Fig. 39) which lie between and engage the projections 492, even when the anvil 298 is at the uppermost limit of its movement. The guards 493 also bear against the rear face of the jack supporting table 483 (see Fig. 31) and supply an easy sliding contact between the adjacent ends of the two tables.

Referring again to Fig. 30: the jack table adjusting screw 486 threads through an adjusting nut 496 and has an unthreaded cylindrical portion which projects downwardly into bearings provided in a projection 498 of the middle tie-piece 316. The adjusting nut 496 seats upon the projection 498. The rigid association of the adjusting screw 486 with its dovetailed tongue 485 prevents said screw from rotating; and consequently, if the adjusting nut 496 be rotated, the screw 486 will be adjusted vertically up or down. The periphery of the adjusting nut 496 is provided with vertical gear teeth 500, which on one side mesh with a gear 502, and on the

other side mesh with the gear teeth 312 upon the periphery of the main jack spindle adjusting nut 310 already described. The gear 502 (see Figs. 30 and 38) is rigidly pinned at the top of a shaft 504, journaled vertically in the frame projection 498; and a handle wheel 506 is rigidly pinned to the lower end of the shaft 504. With this arrangement, when the handle wheel 506 is turned the gear 502 rotates the adjusting nut 496 and thereby adjusts the jack table adjusting screw 486. Also, rotation of the gear 502 is communicated through the adjusting nut 496 to the main jack spindle adjusting nut 310, causing the latter to rotate and adjust the main jack spindle 304. Since it is desirable that the jack table adjusting screw and the main jack spindle, with their respectively associated tables, be adjustable simultaneously and uniformly in the same direction, and since the intermeshing adjusting nuts 310 and 496 are turned in opposite directions by turning the handle wheel 506, it is therefore important that the threads on the main jack spindle 304 and those on the adjusting screw 486 be of equal pitch, but that one be a right-hand thread and the other a left-hand thread. Since the main jack spindle adjusting nut 310 is required to move vertically independently of the jack table adjusting nut 496; and since the latter is required to move vertically independently of the gear 502; it is expedient that the gear teeth 500 on said adjusting nut 496, which is intermediate the other two, have a considerable vertical extent, so that whatever the relative vertical movement of the parts, the various gears will remain in mesh.

To return to the description of the immediate shoe holding means, referring to Fig. 32, the jack shank 472 has a rigid laterally projecting screw lug 508, which (Fig. 39) extends into and through a vertical slot 509 in the jack supporting column 474. This lug 508 is confined laterally in the slot to prevent rotation of the shank 472 and said lug serves also as means for attaching a toe saddle supporting frame 511 to the shank 472. As shown in Fig. 33 this toe saddle supporting frame 511 comprises a horizontally extending arm 513 at the outer end of which the saddle is sustained; and also a vertically extending arm 515, which carries at its top a collar arranged to encircle the shank 472 and steady the frame 511. Thus it will be seen that rotation of the milled adjusting nut 476 not only adjusts the shank 472 and with it the jack L, but also through the lug 508 adjusts the entire toe saddle supporting frame 511 in consonance with the adjustment of the jack L.

Referring to Fig. 30: on the outer end of the arm 513 of the toe saddle supporting frame, is pivoted by a pin 517 a saddle supporting standard 519. This standard

consists of a sleeve into which projects a saddle shank 521 having the saddle N rigidly secured at its upper extremity. The saddle shank 521 is screw threaded and engages a saddle shank adjusting nut 523 which in all respects is similar to the adjusting nut 476. By means of the adjusting nut 523 the saddle can be vertically adjusted independently of any of the other adjustments.

Referring to Fig. 33: the arm 513 of the toe saddle supporting frame 511 has an integral sector 525 the periphery of which is beveled and ribbed to engage a clamping face 527 of a block 529 (see Fig. 38). The clamping face 527 of said block is also ribbed to provide for effective engagement with the sector 525. The block 529 is mounted upon the smooth shank of a clamping screw 531, which screws into the saddle supporting standard 519. A spring 533 encircles the screw 531 and is interposed between the block 529 and the standard 519, tending always to move the block 529 out of engagement with the sector 525. When the clamping screw 531 is screwed up, however, the spring 533 is opposed and the clamping face 527 of the block is forced into rigid engagement with the sector to prevent the saddle supporting standard 519 from rocking on its pivot pin 517. The head of the clamping screw 531 is equipped with a suitable handle 535. A steady pin 537 rigid with the block 529 enters a hole in the standard 519 and guides the block as it is moved back and forth either by the screw 531 or the spring 533. The arrangement just described permits the saddle N to be adjusted toward and from the jack L by rocking it on its pivot, in order to accommodate most effectively shoes of different lengths; and by means of the clamping devices described the saddle can be firmly fixed in adjusted position.

To summarize: By loosening the clamping screw 531, the toe saddle can be adjusted toward and from the jack L to accommodate shoes of different lengths; by turning the adjusting nut 523, the toe saddle can be adjusted independently of the jack L, so as to change the angular inclination of a heel seat relative to a heel; by turning the adjusting nut 476 the jack L and the toe saddle N may be adjusted together to vary the height of the shoe above the jack supporting table; by turning the handle wheel 506 the entire jack table, together with the heel anvil table, can be vertically adjusted. The principal purpose of the adjustment last mentioned will be explained hereinafter. By the means just described a shoe is supported at its heel and toe ends respectively.

Referring to Figs. 37, 38 and 39, the shoe is maintained in its proper relation with the shoe jack L and the toe saddle N by means of a pair of coöperating counter clamps

M, M, which grip the shoe lengthwise through extended contact with the opposite sides of its upper adjacent to the heel seat, thereby holding the shoe and its 5 wooden last firmly in position. The counter clamps M, M and their associated parts are shown assembled with the rest of the machine in Figs. 1 and 2, which exhibit respectively a front and rear view of said 10 clamps.

It is important for the best results that a shoe be held very firmly against displacement because, unless so held, a heel that is slightly out of position or that is thicker 15 at one side than at the other, will displace the shoe when applied to it. Thus, when the top lift is finally applied, it will be askew; and the heel also will be askew when completed, because the heel is shaped 20 or trimmed with the top lift as a guide and unless the latter is leveled and also centered or properly positioned on the shoe, the entire heel will be distorted and out of position. On the other hand, if there be provided 25 shoe clamping means which require the shoe to be pushed into them and pulled out from them, said means are likely to bruise or mutilate the upper leather which is frequently of very delicate quality.

30 This invention contemplates shoe holding means which shall be satisfactory as regards both the manner of engaging the shoe and the security of such engagement. The specific holding means holds the shoe firmly 35 against displacement but it is arranged to disengage the shoe (preferably automatically) before the latter is withdrawn, and to remain in inactive condition until a new shoe is introduced whereupon it becomes 40 effective again. In this manner any possibility of bruising the upper is avoided.

In the preferred form of machine the jack descends between the heel applying and top lift applying operations in order to permit 45 the top lift to be brought into position, and thereafter the jack carries the heel upwardly again to receive the top lift. These movements of the jack in a machine of desired speed capacity, should be extremely rapid. 50 Such circumstances emphasize the importance of a sufficient shoe clamp or holder to prevent displacement of the shoe during the quick changes of position.

The counter clamps, M, M, are mounted 55 upon a counter clamp carriage 539, shown in plan view in Fig. 37, in front elevation in Fig. 38 and in rear elevation in Fig. 39. This carriage 539 has a pair of horizontal rails 541, 541 which (see Figs. 38 and 39) 60 fit in dovetailed tracks 543 extending lengthwise of the jack supporting table 483. With this arrangement the counter clamp carriage 539 is movable horizontally toward and from the front of the machine in a path which is 65 parallel to the movement of the dovetailed

slide 481 which carries the shoe jack L. Projecting upwardly from the rails 541, 541 respectively, and integral therewith, are two vertical supporting standards 545, 545; and these standards have each a vertically 70 disposed dovetailed groove (see Fig. 37) to receive a dovetailed tongue 547 of the vertically movable frame 549, upon which the counter clamps, M, M are pivoted by means of pins 550. As shown in Fig. 38, 75 each dovetailed tongue 547 is divided into an upper portion and a lower portion and the top surface of the latter lies beneath a pin 552, rigid with a standard 545, which limits the upward movement of the tongue 80 547 and the counter clamp frame 549. On each side of the frame 549 (see Figs. 37 and 38) a tractile spring 554 connects a pin 556 on the frame 549 with a pin 557 on a vertical standard 545, the two springs 554, 554 serving to hold the vertically movable counter clamp frame 549 at the uppermost limit of its movement (determined by the pins 552) and to permit the frame 549 to be depressed 85 yieldingly when any excess of pressure is 90 exerted upon the counter clamps M, M. This provision for allowing the counter clamps to yield vertically is of importance since it sometimes occurs that some of the excessive pressure demanded for heelng is 95 communicated to the counter clamps, which, if not permitted to yield, are likely to be distorted, broken or forced out of their proper engagement with the shoe. The counter clamps themselves are appropriately curved 100 as shown in Fig. 37 to give them extended contact with the heel portion of the shoe upper and each clamp is integral with the upper extremity of a counter clamp lever 559. Referring now to Fig. 39, these two counter 105 clamp levers 559, 559 are connected near their upper ends by a tractile spring 561, which tends constantly to move the counter clamps M, M toward each other. When this 110 tendency of the spring 561 is unopposed the counter clamps are forced together, so as to grip the shoe firmly between them. Each counter clamp lever 559 has an integral toothed sector 563 and these sectors intermesh so that any movement of either one of 115 the levers 559 is necessarily accompanied by movement, to an equal extent in an opposite direction, of the other lever 559. Each counter clamp lever 559 also has a toothed sector 565, which meshes with a sector on a bell 120 crank clamp controller 567. The two clamp controllers 567, 567 are pivoted on pins 569, 569 supported in the extreme opposite ends of a cross piece on the vertically movable counter clamp frame 549. With the arrangement of 125 sectors just described, the tendency of the tractile spring 561 is to rock the counter clamp levers 559, 559 toward each other and also to rock the lower ends of the bell crank 130 clamp controllers 567, 567 toward each other.

in the directions of the arrows in Fig. 39; and unless this tendency is opposed the counter clamps M, M are held close enough together to grip a shoe yieldingly between them.

While the operator is arranging a shoe upon the jack and is effecting the various necessary adjustments, it would be more or less inconvenient to have the shoe gripped by the counter clamp and therefore, provision is made for separating the counter clamps automatically when the operator places the various shoe holding means in the position in which they initially receive the shoe. This shoe receiving position is shown in Fig. 33, the shoe jack then standing immediately above the jack table adjusting screw 486. When the shoe holding means are in this position the lowermost 15 ends of the clamp controllers 567, 567, carrying cam rolls 571, 571, respectively, are engaged by clamp opening cams 573, 573, rigidly supported respectively upon brackets 488, 488 at opposite sides of the jack supporting table 483 (see Figs. 37 and 39).

Referring now to Fig. 37, when the shoe has been arranged in proper position upon its support, the jack supporting slide 481 is pushed horizontally toward the rear of the machine as hereinafter described until the shoe jack L assumes position immediately beneath the heel in the heel carrier, thereby replacing the heel anvil I, which was withdrawn rearwardly during the latter part of the first cycle as already explained. During this horizontal movement of the jack slide 481 the cam rolls 571, 571 of the clamp controllers 567, 567 travel along the converging faces (see Fig. 37) of the clamp opening cams 573 and are thereby permitted to move toward each other, with the result that the spring 561 (see Fig. 39) moves the counter clamps M, M toward each other to grip firmly between them the counter portion of the shoe supported upon the shoe jack L. By the time the jack L reaches position beneath the heel in the heel carrier, working engagement between the counter clamps M, M and the shoe on the jack is complete and thus the shoe is supported firmly from beneath, at its heel portion by the jack L, at its toe portion by the toe saddle N, and it is secured against lateral movement by the counter clamps M, M. The rear of the counter portion of the shoe is held against a shoe back stop 587 hereafter more fully described.

Referring to Fig. 5, which shows a vertical transverse section of the heel anvil supporting table 300, said table is provided with dovetailed tracks 575 which, when said table is in its lowermost position (see Fig. 33), exactly register with the dovetailed tracks 543, 543, on the jack supporting table 483. Hence, the tracks 575 and 543 to-

gether supply continuous ways on which the horizontal rails 541 of the counter clamp carriage 539 may be moved from front to rear of the machine, and vice versa. When the counter clamp carriage 539 and the shoe jack slide 481 have been drawn to the front of the machine to permit the operator easy access thereto for arranging the shoe in position (see Fig. 33), the shoe holding means rest entirely on the jack supporting table 483, independently of the heel anvil table 300; and the latter is permitted to move through its vertical reciprocation during the first cycle independently of the shoe holding means and the jack supporting table 483. When, however, the shoe holding means are pushed rearwardly to carry the heel seat of the shoe into registry with the heel (see Fig. 32, the heel anvil I having been retracted as there shown) the horizontal rails 541 (Fig. 39) of the counter clamp carriage stand both in the dovetailed tracks 543 of the jack supporting table 483 and in the dovetailed tracks 575 of the anvil table 300, and thus contribute to bind said tables 300 and 483 rigidly together so that the latter is compelled to partake of the vertical reciprocation of the former when the main jack spindle 304 is given its vertical movement.

Referring again to Fig. 5, the dovetailed way in the anvil table 300 which receives the anvil slide 298 exactly registers (when the table 300 is in its lowermost position) with the shoe jack slide 481, and when the anvil slide has been retracted during the first cycle the two dovetailed grooves just mentioned supply a continuous track upon which the jack slide 481 may be moved horizontally toward the rear of the machine or vice versa. When the counter clamp carriage 539 is moved rearwardly to place the shoe in proper position beneath the heel, the slide 481 is also moved to the same extent and to the same end, the two being preferably moved together. When in its final rearmost position, the jack slide 481 lies in part in its dovetailed groove on the anvil table 300 and in part in the dovetailed groove on the jack table 483, and consequently, it coöperates with the horizontal rails 541 of the counter clamp carriage 539 to bind the jack table and the anvil table rigidly together.

Referring to Figs. 32 and 39, a cross tie piece 577, rigid with the counter clamp carriage 539, supplies a stop face which abuts against a stop 579 on the heel anvil slide 298; and said stop serves to prevent the shoe holding means from being moved onto the anvil table 300 while the anvil I is in its active position beneath a heel. Thus during the first cycle when the anvil is required to reciprocate vertically independently of the shoe holding means, the latter are effectively prevented from tying together, in the man-

ner described, the jack table and the anvil table. Also the stop 579 strikes against the stop face on the counter clamp carriage 539 and drives the latter forwardly to remove 5 the shoe holding means from the anvil table 300, when the anvil is replaced beneath the heel carrier in the third cycle preparatory to another pricking operation.

Referring to Figs. 32 and 38, the rear-most position of the shoe holding means is 10 determined by an adjustable stop screw 581 which threads into a front cross tie piece 583 of the counter clamp carriage 539. When the carriage is pushed back into position the screw 581 abuts against a stop face 585, supplied upon the front of the jack table 483, and the latter being laterally rigid further movement of the carriage is prevented.

20 Rigidly secured at the upper ends of the dovetailed tongues 547 (see Fig. 37) of the vertically movable frame 549 is a shoe back stop 587. While this shoe back stop is capable of yielding vertical movement with 25 the counter clamp frame 549 it is rigid with the counter clamp carriage in so far as movement of the latter rearwardly on the machine is concerned and consequently, the coöperation of the stop screw 581 and the 30 stop face 585 serves to determine the rear-most position of the shoe back stop 587; and the shoe back stop, in turn, determines the rear-most position of the shoe which, carried upon the jack, may be thrust rear- 35 wardly until the rear of the counter portion of the shoe abuts solidly against the back stop.

During the first cycle while the machine is under the control of the boy, the shoe 40 holding means, including the jack, the toe saddle and the counter clamps all occupy approximately the positions shown in Fig. 31. Thus, they are all easily accessible to the operator who takes a shoe mounted on its 45 wooden last, places the steel shod socket of the last over the last pin on the jack L and the toe of the shoe on the toe saddle N. Then, by means of the various features of adjustment already described, the operator 50 arranges the shoe in the position which he desires it to have on the jack and saddle, preferably disposing the heel seat so that it shall be approximately horizontal. When the shoe has been thus arranged it is ready 55 for the attachment of the heel. When the first cycle comes to an end the heel anvil has been retracted to its rearmost position to make way for the shoe holding means which are shoved back by the operator until 60 the heel seat of the shoe registers with the recently pricked heel. The jack table and the anvil table being rigidly tied together, as already described, if the adjusting screws 490, 490 (see Fig. 38) be properly manipulated 65 said tables and the entire shoe hold-

ing means may be adjusted laterally cross-wise of the machine so as to adjust the heel seat laterally relative to the heel. The shoe may be adjusted lengthwise by turning the adjustable stop screw 581 so as to vary the 70 rearmost position of the shoe holding means determined by it. Also the heel in its carrier may be adjusted lengthwise of the shoe by turning the heel back stop adjusting screw 190 (Figs. 1 and 19) which, as already 75 stated, is readily accessible to the operator. When all of these adjustments have been effected to the satisfaction of the operator he is ready to proceed with the attachment of the shoe.

Different styles of heels vary considerably in height; and even when heels are intended to be of exactly the same height a certain amount of variance is likely to occur. If then it be desired to compress each heel as a 80 part of the heel attaching operation it is desirable that some provision be made for compressing heels uniformly, irrespective of variations in height. This is especially important when heels are being attached to 85 shoes which are mounted upon wooden lasts and is less important when the usual wooden last is replaced by a steel jack or the like, preparatory to the heel attaching operation. In the later case the steel jack or the like is 90 sufficiently stable to sustain the abnormal pressure occasionally involved in compressing heels of unusual thickness greater than that anticipated by the particular adjustment of the machine. In practice, it is well 95 100 nigh impossible to anticipate these variations in thickness of heels so that any one adjustment of compressing means will suffice for all heels and, consequently, the compressing means are likely to be subjected at 105 intervals to severe strains which would tend at least to warp and probably to shatter a wooden last. For these reasons and for the purposes of the specific machine which has been the subject of the foregoing description, 110 it is preferred that some provision be made for a heel measuring operation which shall determine in advance the initial position of the compressing means relative to the heel so that when said compressing 115 means are moved thereafter a predetermined distance the heel will be compressed to the extent of said predetermined distance regardless of the thickness of the heel.

The preferred form of machine shown in 120 the drawings is designed to compress each heel which it attaches to a shoe, one eighth of an inch; *i. e.* when attached, each heel is intended to have a thickness which is substantially one eighth of an inch less than 125 that which it had before attachment. In order to secure this degree of compression for each heel, irrespective of the initial thickness of the heel, the present invention, as embodied in the preferred machine, con- 130

templates that the shoe shall be moved toward the heel until the heel seat rests snugly against the heel; and that thereafter the heel seat shall be positively pressed against the heel through a distance of one eighth of an inch in order to compress the heel. The movement of the shoe until the heel seat abuts against the heel in the first instance is designated the heel measuring operation, and according to the preferred embodiment of the invention this operation is performed manually by the operator who holds the heel seat against the heel until the beginning of the compression. It is evident that, if the heel seat is moved invariably through a predetermined distance to compress the heel after the former has been placed in contact with the latter, the heel will be compressed to the extent of said distance regardless of its height. At this stage it may become expedient to adjust the height of the shoe by turning the handle wheel 506 (Fig. 32) and thereby moving the heel seat upwardly or downwardly, as the case may be. This adjustment, while it may be of convenience in connection with the attachment of heels on the specific machine which has been described, is of greater importance when said machine has been changed so as to adapt it for eliminating the heel measuring operation. In the latter case it is expedient to effect such vertical adjustment of the shoe relatively to the heel as may be required to suit heels of different heights, by means of said handle wheel 506.

When the shoe is in position to register with the heel in its carrier, the jack table 483 and the heel anvil table 300 are secured rigidly together by the counter clamp carriage 539 and the jack slide 481. Hence, in order to elevate the shoe until the heel seat abuts against the heel (*i. e.* in order to perform the measuring operation) it is convenient to apply a lifting force to the sleeve 305 encircling the main jack spindle 304. When the sleeve 305 is elevated, the main jack spindle 304 is also elevated, together with the heel anvil table 300. The latter being rigidly connected with the jack supporting table 483, said table is also elevated.

Referring to Figs. 1 and 32, the lifting force for the measuring operation is applied to a rigid stud 589 on the jack spindle sleeve 305, through the agency of a measuring lever 591, pivoted at 593 on a pin supported in bearings depending from the middle tie piece of the machine frame. The opposite end of the measuring lever 591 is arranged to be depressed for lifting the jack spindle sleeve 305 by means of a hand lever 595 (Fig. 3), fulcrumed upon a standard E of the machine frame, and having its handle readily accessible to the operator's right hand (see Fig. 1). The relative dimensions of the levers 591 and 595 are such that the

force expended by the operator in depressing the latter by its handle is compounded so as to facilitate the lifting of the jack spindle sleeve 305 and the various parts carried with it.

70

Referring to Fig. 32, the jack spindle sleeve 305 and the parts carried with it in the measuring operation are shown in elevated position, said sleeve and the main jack spindle 304 having carried upwardly 75 the anvil table 300, the jack supporting table 483 and the jack table adjusting screw 486 with its adjusting nut 496, said nut being prevented from rotating on the threads of the screw 486 by the fact that the gear 502 80 under the control of the handle wheel remains stationary. By depressing the handle of the lever 595, the operator lifts the shoe until the heel seat abuts firmly against the bottom of the heel held in the carrier, thereupon the heel is ready to be compressed by positive elevation of the shoe. That is to say, all is in readiness for the beginning of the second cycle, which is initiated by the operator depressing his treadle and thereby 85 forcing the push pawl on said treadle against the first tooth of a pair on the operator's controller ratchet.

Prior to the start of the second cycle a group of nails is positioned in holes in the nail block H, and a series of drivers on the pricking and driving beam 412 register with said nails in position to drive them upon being depressed. When the machine starts for the second cycle the jack actuating cam 100 308 occupies the position shown in Fig. 30, the jack lifting frame 306 being then at its lowermost position. By means of the cam rise 340 (see Fig. 30) of the jack actuating cam 308 the jack lifting frame is elevated 105 through the first step of its upward movement (*i. e.* through one and one eighth inches) this elevation being effected while the jack spindle locking nut 363 is still free to rotate. Thus, the elevation of the jack 110 lifting frame is idle as to any effect upon the shoe during its first step of elevation, since then it does not move the main jack spindle 304. Presently, however, (referring again to Fig. 30) the cam rise 342 on the jack actuating cam 308 becomes active. A moment previously the rotation of the jack spindle locking nut 363 is arrested so as to render the jack lifting frame and the main jack spindle rigid each with the other. Consequently, during the further elevation of the jack lifting frame (through one eighth of an inch in the specific machine) the main jack spindle is positively elevated to force the heel seat of the shoe against the heel 115 and to compress the latter. Thereupon, the dwell 344 of the jack actuating cam 308 becomes effective to hold the heel compressed between the heel seat of the shoe and the nail block H, in which repose the nails. 120 125 130

During this dwell the pricking and driving beam 412 descends and causes the drivers to engage the tops of the nails and drive them through the previously pricked holes 5 in the heel, thereby upsetting or clenching the spatulated points of the nails against the steel shod heel of the wooden last within the shoe. In this driving operation the annular collars of the nails are pressed against 10 or embedded in the outer face of the heel, a short length of each nail being left projecting beyond the face of the heel for the reception of the top lift.

Referring again to Fig. 30, after the dwell 15 344 of the jack actuating cam 308 has passed, the down track 346 permits all of the parts to descend again to their normal lowermost positions, whereupon the cycle comes to an end when the main shaft B has completed 20 one half a revolution and the machine is automatically stopped by the auxiliary clutch disengaging mechanism heretofore fully explained.

I believe I am the first to provide in a 25 unitary heelng machine, pricking and nailng means (the latter necessitating the removal and substitution of shoes to be heeled) wherein the two operations in whole or in part take place concurrently; or wherein the 30 operator and his helper may be simultaneously at work, the one in connection with the pricking and the other in connection with the attachment of a heel previously pricked under the guidance of the first. Heretofore, where it has been attempted to prick and nail upon one and the same machine, the 35 heeling has been delayed to await the pricking and thus the operator's output has been reduced. This has led to the practice of 40 pricking the heels, or pricking and loading them, before introducing them to the heelng machine: in other words, this has led to a disintegration of the nailng process which comprehends in its completeness both pricking and loading, as well as driving. This 45 division of heelng into separate parts presents many objections; and as a result the pricking as a separate operation has been largely abandoned commercially. It is 50 highly desirable, however, to prick holes since thereby the quality of work is materially improved, and the nailng is greatly facilitated. This invention permits the 55 pricking and nailng to be accomplished upon the same machine; and permits the former to be performed during the period required for the change of work or shoes, so that the pricking process (so far as it is separable, for purposes of discussion, 60 from the nailng) may take place during what may be called the inactive nailng period, so that no time is lost. In other words, the nailng and attendant operations proceed uninterruptedly and without delay 65 and the pricking is accomplished at the nail-

ing point of the machine with all the advantages of avoiding movement of the heel from one position to another to be acted upon in different places with large possibility of errors; as demanded when the pricking and nailng are separately performed.

During the second cycle the heel is securely attached to the shoe by the nailng operation and thereafter the heel is no longer dependent upon its carrier but travels 75 with the shoe so that upon the descent of the shoe the heel leaves its carrier. When the heel has departed sufficiently far from its carrier to leave the latter clear, the top lift shifting cam 264 (Fig. 2) moves the heel 80 and toplift carriers crosswise of the machine to bring the toplift into position beneath the nail block H in registry with the recently attached heel. Hereupon the operator may resort to the various adjustments of the shoe 85 holding means for bringing the shoe into proper relation with the top lift and he may also adjust the top lift lengthwise of the shoe by means of the toplift back stop adjusting screw 238. When these adjust- 90 ments have been effected all is in readiness for the top lift spanking operation. Preliminarily to the top lift spanking operation, it is preferred to measure the heel and top lift together, in order that the positive 95 second step of elevation of the shoe and attached heel shall be just sufficient to spank on the top lift but not sufficient to compress the top lift unduly and jam the projecting ends of the nails through the top lift. To 100 this end during the period of rest succeeding the completion of the second cycle, the operator again depresses the handle lever 595 and thereby elevates the shoe and attached heel until the heads of the nails projecting 105 from the latter abut against the top lift in its carrier. The push pawl on the operator's treadle is at this stage in engagement with the second tooth of a pair on the operator's controller ratchet and hence, the operator re- 110 mains control of the machine during this time and, upon depressing his treadle, starts the machine for the third cycle.

Referring to Fig. 30, prior to the beginning of the third cycle the jack actuating 115 cam 308 has been rotated through one hundred eighty degrees from the position shown in said Fig. 30 and, therefore, the cam roll 332 rests at this time upon the dwell 348 of the cam 308. When the machine starts for the third cycle the cam rise 350 first elevates the jack lifting frame 306 idly, as to any effect upon the heel or top lift, and thereafter said cam roll enters the cam rise 352, to begin the second step of elevation of 120 the main jack spindle and the parts carried by it. At the beginning of this second step of elevation the rotation of the jack spindle locking nut 363 is again arrested to render 125 the jack lifting frame and main jack spindle 130

mutually rigid, and hence, the second step of elevation of the jack lifting frame 306 under the influence of the cam rise 352 positively moves the attached heel toward the 5 top lift and presses the projecting ends of the nails into the latter. Thus, the top lift is securely attached to the heel and after a short dwell 354 of the cam 308 the shoe, with its attached heel and top lift, descends 10 under the influence of the down track 356 of the cam 308 to the dwell 358 at the end of which the machine is stopped, leaving the cam 308 in the position shown in Fig. 30, ready for the commencement of a new first 15 cycle.

Referring now to Fig. 3 prior to the beginning of the third cycle the pricking and driving cams 438 and 440 have been rotated by the second cycle through one hundred eighty degrees from the position shown 20 in said Fig. 3. Thus, the pricking and driving beam is at the uppermost limit of its movement and the cam rolls 436 and 434 are about to enter upon the dwells 597 and 598, 25 respectively, on the cams 440 and 438. These dwells maintain the pricking and driving beam at the uppermost limit of its movement throughout the third cycle, since neither the pricking awls nor the drivers 30 have any function during this cycle. At the end of the third cycle the cams 438 and 440 have returned to the positions shown in Fig. 3 and are ready to depress the awls when a new first cycle shall have been initiated. 35 During the third cycle the drivers which were active during the second cycle are replaced by the pricking awls, as heretofore described, preparatory to the pricking operation in the next first cycle.

40 Hitherto this discussion of the preferred pricking, nailing, spanking and attendant operations has been based upon the assumption that, at proper times, nails were delivered automatically to the nail block H in 45 position to be driven by a subsequent nailing operation. It remains now to describe the manner in which nails are thus delivered.

The specific mechanism preferred to be employed for delivering nails to the nail 50 block includes a source of supply of nails; means to receive nails therefrom; and nail conveying means. For the present this entire mechanism may be considered as independent of those parts of the heelng machine hereinbefore described, postponing an 55 explanation of the important coöperation of said mechanism with other features of the machine, until the former is fully understood. Suffice it to say at this time that the 60 source of supply of nails, and the means to receive nails therefrom (see Figs. 3 and 4) are mounted at the right hand side of the rear of the machine, upon a shelf 600 supported by a bracket 602 projecting from a 65 standard E of the machine (see also Fig.

2); and that the conveying means are intermediate the rest of said mechanism and the nail block H.

It will be observed in the machine here illustrated that the nail supplying means is 70 located at the rear of the machine (considering the front thereof to be where the operator stands) and that it occupies a position slightly to one side of the point at which the nails are driven (see Fig. 40). By this arrangement the entire mechanism is removed 75 from any position in which it could interfere with the operator, and is, at the same time, so close to the nailing point that the travel of the nail carrier, which must be quick and 80 without violence, is reduced to a minimum.

I prefer to load the nails intended for the heel, singly from a single raceway or source of supply, rather than from a plurality of sources or raceways, because it has been 85 found that the delays in the operation of the machine are much more largely attributable to difficulties arising in the nail supplying mechanism than to anything else; and by reducing the number of raceways 90 and coöoperating nail delivering or separating means to a minimum (as to one) these delays are proportionately eliminated. In receiving nails from a single raceway, however, a step by step operation is usually necessary, so that starting from one end of the series of nails adjacent one breast corner, the supply progresses in a substantially 95 horseshoe-shaped series, to the opposite extremity of the series adjacent the other 100 breast corner. If the nail supply could be placed conveniently at the front of the machine toward which the breast of the heel ordinarily faces, it would be found that the 105 position of the horseshoe-shaped series of 110 nails in the carrier would be substantially that required for applying the same to the heel and a compact arrangement of the machine parts would be practicable. In placing the supplying mechanism at the back 115 of the machine, however, the disposition of the series of nails supplied to the carrier is approximately the reverse of the disposition 120 which the series is desired to have when inserted in a heel. For this reason supplying mechanisms heretofore, have been so arranged that the carrier movement would involve a reversal of the disposition of the nail series so as to present the series finally 125 in heelng position facing in the right direction. When reducing the distance of the carrier's travel, as is desirable, it is not convenient to obtain this reversal of the nail series from the nail carrier movement alone; and I have therefore (as I believe for the 130 first time in the art) provided the nail carrier with an additional supplementary or auxiliary movement capable of giving to the nail series (whether singly or plurally assembled) a change of disposition additional 130

to that resulting from the mere bodily transportation of the carrier from supply to delivery position. To this end, in the specific illustrative machine, the carrier is caused to revolve more or less upon itself while moving bodily from receiving to delivering position.

The source of supply of nails preferable to be employed consists of an independent nail magazine which is filled apart from the feeding mechanism, the latter having no provision for assorting nails. This magazine may be readily removed from the machine and may be filled in any practicable manner, as by hand or by appropriate nail assorting means. Several of these magazines, some containing different sizes of nails, are intended to be kept in readiness to be placed on the heelng machine whenever the supply of nails in one has been exhausted, or whenever it is desired to change the size of nail by which heels are being attached. This arrangement possesses many advantages which will be apparent to those skilled in the art. By way of illustration, it may be said that the use of a ready filled magazine serves to reduce the complication of the machine as a whole, with the result that accidents are less likely to occur, which would interrupt the operation of the machine and delay its work. The preferred form of magazine presently to be described, is supplied, before being introduced to the machine, with a considerable number of nails arranged in perfect readiness to be removed for delivery to the nail block, and thus the various exigencies of nail assorting are avoided. Moreover, a single nail assorting machine, or a series of such machines adapted to load different magazines respectively with nails of different sizes, can be used to assort nails for any number of heelng machines, thereby avoiding reduplication of assorting mechanisms to provide one for each heelng machine in the manner frequently adopted heretofore.

While various features of invention pertaining to the nail feeding mechanism might be applied advantageously to machines comprising nail assorting means, it is considered expedient to secure such benefits as have been suggested, by eliminating entirely from the construction and operation of a heelng machine, all mechanism for assorting nails; and a convenient manner of providing for this elimination is exemplified in the preferred machine herein described.

It has already been suggested that the machine shown in the drawings is arranged for attaching heels by means of a preferred type of nail. To suit this preference the specific magazine about to be described (as well as the other parts of the mechanism) is especially adapted to the characteristics of these nails.

Referring to Figs. 3, 43, 45 and 47, the

nail magazine is shown as a raceway 604 composed of parallel side plates 606 (see section, Fig. 47) having their upper edges flanged inwardly over stiffening plates 608. The adjacent edges of said flanges are flush respectively with the plates 608, and together said flanges and plates form a nail receiving slot 610. The walls of said slot 610 are spaced apart a slightly greater distance than the diameter of a nail shank, and a slightly less distance than the diameter of a nail collar. Hence if the point of a nail be dropped into the slot 610 the nail will be suspended freely therein by its collar which will rest upon the smooth upper faces of the flanges of the side plates 606. Spaced above the flanges a slightly greater distance than the length of nail head projecting beyond its collar, is a cover plate 612 which overlies the nail heads and, while permitting them to pass freely beneath it, prevents their escape from the slot 610. For convenience of attachment the cover plate 612 is supplied by one face of an angle iron attached to brackets 614 rigid with the side plates 606.

When in proper position on the machine the race-way is supported between the bifurcations of stationary brackets 616, 616, the raceway being so held in said brackets as to incline at a considerable angle to the horizontal, thereby causing nails in the slot 610 to slide downwardly by gravity. At the lower end of the raceway (see Fig. 48) is a spring detent 618 which engages the head of the lowermost nail, preventing its escape from the raceway and by it detaining the whole series of nails.

Referring to Fig. 45, secured to the side plates 606 at the lower end of the raceway are guides 620 in the form of plates one of which (see Fig. 48) supplies a notch which is engaged by a bolt 622 slidably mounted in a part of the frame of the mechanism. A leaf spring 624 connected to said bolt holds it yieldingly in the notch and permits it to be withdrawn for removing the raceway.

The nails in the raceway, being suspended from an inclined track by their collars, tend to hang substantially perpendicularly to the length of the raceway. The extreme end of the raceway, however, makes a turn so that its nail supporting flanges lie horizontally, thereby contributing to allow the lowermost nail to hang vertically at a considerable angle to the next following nail. Moreover, the lowermost nail having its head held by the detent 618, the downward pressure exerted by the remaining nails tends to throw the point of the lowermost nail forwardly and to separate said point widely from the next following nail. The angle which thus intervenes between the two endmost nails facilitates the insertion therebetween of a separator 626 which serves

to liberate the lowermost nail, and at the same time to prevent the escape of the next nail until the former has been properly disposed of.

5 Referring to Fig. 49, the separator 626 stands normally across the end of the raceway and acts as a gate against which the lowermost nail rests in its substantially vertical position as just described. This separator 626 (see Figs. 46 and 50) is a vertically disposed plate mounted upon the end of a horizontal slide 628 arranged in ways on the casting constituting the frame of the nail feeding mechanism.

15 As shown in Figs. 44 and 46, the opposite end of the slide 628 from the separator 626 has a rigid pin 630 which projects into an elongated slot in one end of a bell crank separator lever 632. This lever 632, pivoted 20 at 634 (Fig. 47), has a cam roll 636 in position to be engaged by a separator cam 638 on a shaft 640 which is the main shaft of the nail separating mechanism. This shaft is driven in the direction of arrow 642. The 25 cam 638 is a surface cam and serves intermittently to rock the lever 632 (clockwise in Fig. 47) to withdraw the separator 626 from its normal position in front of the raceway, said lever and the separator being returned 30 to normal position by means of a tractive spring 644, attached at one end to the upper arm of the lever and at its other end to a pin on the frame casting.

When the separator 626 is removed from 35 in front of the raceway as shown in Fig. 50, the lowermost nail moves downwardly to the extreme end of the raceway and its point swings forwardly, thereby spacing the nail still farther from the next following nail.

40 When the separator 626 returns (to the left Fig. 50), its upper pointed corner is interposed between the said two nails, preferably underneath their collars and, progressing farther, acts by a bevel (inclined to the rear 45 as viewed in Fig. 50) to pick the lowermost nail from the raceway and forcibly disengage its head from the detent 618. At the same time the separator serves as a gate to close the end of the raceway and prevent 50 the escape of any nail other than the one intended to be removed. Obviously, if the separator be prevented from reciprocating across the end of the raceway no nails will be removed and the entire mechanism will 55 be temporarily inoperative as to its intended nail feeding office. When a nail is liberated by the separator it is introduced to a nail barrel 646 about to be described.

60 The nail barrel 646 (Fig. 45) consists, in general, in a vertically disposed cylinder, pivoted on its axis and having a series of vertical peripheral nail carrying grooves in each of which a nail is deposited by the action of the separator. The barrel is rotated 65 step by step on its axis in order to bring the

nail carrying grooves in succession within the sphere of activity of the separator and to remove each groove as it is supplied with a nail. When nails have been deposited in the grooves, to the number desired for attaching a heel, the rotation of the barrel is finally arrested until the nails are discharged from the barrel into chutes which conduct them toward the conveying means already referred to. A preferred form of nail barrel is shown in front elevation in Fig. 45; and in side elevation (looking toward the left in Fig. 45) in Fig. 50.

70 Referring first to Figs. 46 and 50 the barrel 646 is rotatably mounted on a headed pin 648 rigidly secured to a bracket 650 integral with a barrel slide 652 (see also Fig. 44). The slide 652 is dovetailed to fit a seat provided upon a part of the frame, this arrangement permitting the barrel to be readily removed from the machine for purposes 80 later to be explained. As shown in Fig. 46, the slide 652 is held in position by a locking pin 654 extending through the slide and normally projected into a hole in the stationary frame by a leaf spring 656.

90 Encircling the barrel 646, throughout the greater part of its periphery, is a cylindrical casing 658 rigidly depending (as best shown in Fig. 46) from the bracket 650; and rigidly secured to the lower base of the barrel, 95 externally to the casing 658, are a barrel ratchet plate 660 and a barrel locking plate 662. As shown in Fig. 52 a tooth of the ratchet plate is engaged by a pawl 664 by which said plate is rotated from time to 100 time; and a barrel latch 666 projects into one of the peripheral notches on the locking plate 662.

105 Referring to Fig. 52; the pawl 664 is pivoted at one end of a bell crank pawl driving lever 668, fulcrumed at 669, the other end of which carries a cam roll engaged by a pawl cam 670 on the main shaft 640 of the separating mechanism. The pawl 664 is kept to its contact with the ratchet plate 660 110 by a tractive spring 672 attached at one end to the tail of the pawl and at its other end to the lever 668. In order to preclude the possibility of said spring throwing the pawl out of contact with the ratchet plate when 115 the former is returned to engage a new tooth on the latter, the pawl is provided with a guard finger 674 which, when the pawl is retracted (toward the top of the sheet in Fig. 52), strikes on the edge of the ratchet plate 120 and confines the pawl to its proper path.

125 The barrel latch 666 is rigidly and adjustably mounted upon one end of a barrel locking lever 676, fulcrumed at 678, the other end of which has a cam roll engaging a barrel locking cam 680. The cam 680 acts only to withdraw the latch 666 from engagement with the locking plate 662 (*i. e.* to move the lever 676 contra-clockwise in Fig. 52); and 130

the latch is thrown into renewed engagement with the locking plate by a tractile spring 682 secured (see Fig. 44) at one end to the lever 676 and at the other end to the frame. The point of the latch 666 is wedge shaped to fit the angular notches of the locking plate, and therefore the latch serves also to center said plate accurately in position.

The time relations of the pawl cam 670 and the barrel locking cam 680 are such that the latter withdraws the latch from a notch in the locking plate 662 just before the former rocks the pawl lever 668 (contra-clockwise in Fig. 52) to rotate the ratchet plate 662 and therethrough the nail barrel 646; and the locking cam 676 releases the latch, permitting it to be pressed toward the locking plate by the spring 682, in time to let the latch enter the next following notch on the locking plate immediately the pawl finishes advancing the barrel through one of its steps of rotation. In this manner the barrel is positively rotated step by step, and is locked securely in position when at rest.

The time relations of the separator cam 638, and the cams 670 and 680 are such that the separator is released by its cam and thrown forwardly by its spring 644 (to the left Fig. 50) shortly after the nail barrel has completed one of its steps of rotation and has thereupon been locked in position. During the operation of the mechanism the nail barrel when so locked in position presents one or another of its nail receiving grooves 684 in proximity to the separator and raceway. The grooves 684 are vertically disposed upon the periphery of the barrel and each is preferably of slightly greater length than that of the longest nail intended to be used, and each also extends clear through the bottom of the barrel so that, under proper circumstances the nails can drop vertically downward, endwise, and so depart from the barrel. The number of grooves 684 provided upon the nail barrel equals the number of nails desired to be used in attaching one heel to a shoe; and these grooves are disposed at equal distances apart except that a space intervenes between two of them (see Fig. 48) which is double the space intervening between any other pair. Thus, for the purposes of the specific mechanism, as shown in Fig. 48, there are seven grooves 684, two of which are spaced apart by a blank space 686 of approximately ninety degrees, while all the others are spaced apart approximately forty-five degrees.

There are upon the ratchet plate 660 eight teeth, one corresponding to each groove 684 and one corresponding to the blank 686, thus providing for eight rotary steps of the barrel, or one step in excess of the number of nails desired to be separated from the raceway by the separating mechanism.

On the barrel locking plate 662 there are eight notches for the latch 666, each notch corresponding to a tooth on the ratchet plate 660; and each notch provides means for holding the barrel in its position of rest at the end of one of the eight rotary steps.

With the arrangement just described each of seven rotary steps of the barrel will present a nail receiving groove proximate to the raceway and separator; while the eighth step will present only the blank 686.

The cylindrical casing 658 of the barrel is cut away tangentially to the latter at its point of nearest approach to the separator thereby leaving free passage (except for the spring detent) for a nail from the raceway to the periphery of the barrel when the separator is retreated from in front of the former. The separator moves preferably tangentially to the barrel; and when it is in position to close the end of the raceway (see Fig. 49), said separator by its opposite face serves also to close laterally a groove 684 if one be then stationed adjacent to the raceway.

As already described, whenever the separator is retreated to the position shown in Fig. 50, the lowermost nail in the raceway enters into position to be engaged by the separator on its return trip and to be removed thereby from the raceway. Assuming a nail groove 684 to have been presented in proximity to the raceway (see Fig. 49) the same movement of the separator which picks the nail from the raceway, acts also to push the nail into the adjacent groove 684, further movement of the separator serving to inclose the nail in the said groove and at the same time to preclude the removal of another nail from the raceway. When the nail has been thus deposited and inclosed in a nail groove, the barrel is rotated through another step to bring another groove into nail receiving position; the separator retreats and then returns to deposit another nail in the recently presented groove; and so on until all the grooves are filled.

When the nail supplying mechanism is at rest the blank 686 stands always next the raceway as shown in Fig. 48; the separator occupies its position of retirement shown in Fig. 50; and the pawl, the latch and their cams stand as shown in Fig. 52. The mechanism is arranged to stop automatically always with the parts in these positions.

When the mechanism is started, the first revolution of the main shaft 640 withdraws the pawl and then drives it forward to rotate the barrel and bring the first groove 684 into nail receiving position. Under ordinary circumstances this first revolution of the shaft 640 would also permit the separator to advance and pick off a nail but this is postponed until the second revolution (when a groove is in position to receive the liber-

ated nail) by temporarily detaining the separator from its accustomed movement by means presently to be described. During the second revolution of the shaft 640, however, the separator is released; and thereafter with seven revolutions of the shaft, seven nails are removed from the raceway and deposited respectively in the seven grooves in the barrel. When this has been done the mechanism is automatically stopped with the parts in the positions shown in Figs. 48, 50 and 52. Thereupon the seven nails are in readiness to be discharged from the barrel.

15 The means by which the nails are retained in the nail receiving grooves 684 is now necessary to be considered. The position of the raceway relative to the barrel is such that a nail issuing from the former has its collar elevated above the top of the barrel; hence when the nail is deposited in a groove on the barrel its collar overlies a portion of a retaining plate 688 mounted upon the top of the barrel.

20 Referring to Figs. 45, 48, and 48^a: the retaining plate 688 is arranged to rotate concurrently with the barrel about the pin 648; and also said plate is capable of limited oscillation about said pin relatively to the barrel.

25 The barrel carries a rigid pin 690 which projects upwardly through an elongated slot 691 (see dotted lines Fig. 48) in the retaining plate 688. Fulcrumed on this pin 690 is a lever 692 carrying at one end an upwardly projecting rigid stud 694 which engages a cam 695 fixed upon the under side of the barrel supporting bracket 650 (see Fig. 50). The cam 695 is spaced somewhat 30 above the retaining plate 688 and a portion of the lever 692 extends beneath it. A notch in the lever 692 engages a pin 697 rigid with the retaining plate. When the lever is rocked, therefore, upon its pivot 690 (which, 35 be it remembered, is rigid with the barrel), said lever acts with the effect of a bell-crank upon the pin 697 to oscillate the retaining plate 688 relatively to the barrel. The lever 697 is rocked to this end, in one direction 40 (see arrow, Fig. 48) by the cam 695 which has a long dwell 698; and in the opposite direction by a lug 699 (see Fig. 50) depending from the barrel carrying bracket 650, said lug being located opposite to a depression 45 in the cam 695 into which the stud 694 of the lever 692 is pushed upon passing between said lug and depression. Oscillation of the retaining plate 688 resulting from movement of the lever 692 in the direction 50 of the arrow in Fig. 48, is limited by the end of slot 691 striking the pin 690; and oscillation in the opposite direction is limited by the lever stud 694 contacting with the cam 695.

55 In the circumference of the retaining

plate 688 are radially reentrant recesses 700 corresponding in number and location to the nail receiving grooves 684 on the nail barrel. One side of each recess 700 supplies a nail supporting lip 702. A similar lip 704 (Figs. 45 and 50) projects upwardly from the barrel into each recess immediately adjacent to a nail receiving groove 684, said lips being rigid with the barrel, and their tops being flush with the upper surface of the retaining plate 688. When the retaining plate stands at one limit of its oscillation each pair of lips 702, 704 exactly registers with a groove 684 in such manner that said groove is substantially continuous and of uniform dimensions from the bottom of the barrel to the top of the retaining plate; but when said plate stands at the other limit of its oscillation the lips 702, 704 are positioned nearer to each other than before, being spaced apart a less distance than the diameter of a nail collar and a slightly greater distance than the diameter of a nail shank. The lips 702, 704 are held thus close together when the lever stud 694 rides on the dwell 698 of the cam 695, which occurs during all the time that nails are being deposited in the nail receiving grooves of the barrel. Consequently, when a nail is introduced to a groove, its collar elevated above the top of the barrel, the nail will be suspended in the groove by its collar resting against a pair of lips 702, 704. The nails remain thus suspended until the stud 694 strikes the rigid lug 699 whereupon the lever 692 is rocked to oscillate the retaining plate, separate the lips 702, 704, and release the nails which are then free to drop vertically downward and depart from the barrel. The lever stud 694 engages the lug 699 to release the nails as just described, when the barrel completes its last rotary step bringing the blank 683 opposite the raceway, and the parts come to rest in the positions shown in Figs. 48, 50 and 52. Thus one load of nails (*i. e.* enough to attach one heel) is separated from the raceway and discharged from the barrel between the beginning and end of one operation of the separating mechanism.

60 As clearly shown in Fig. 45, each nail receiving groove 684 communicates at its lower extremity with a cylindrical vertical hole 706 extending from the top of the ratchet plate 660 through said plate and the locking plate 662. When the nails in the barrel, therefore, are finally released by separation of the nail supporting lips 702, 704, said nails pass freely downward from the barrel and through the holes 706, 706. Upon issuing from the latter the nails are immediately brought under the control of a nail arranging distributor which preferably disposes them in the mutual relations they are desired to have when driven through a heel. A convenient form of distributor is shown in Figs. 130

45, 46 and 50. Referring now to Fig. 46 this distributor comprises a rigid frame 708 integral with a slide 710 arranged in a dovetailed slot on the frame casting of the mechanism to permit its ready removal and replacement. Said frame is provided with a handle-piece 711 for this purpose. The slide 710 is preferably supplied with a spring held locking bolt 712 arranged to project through the slide into a hole in the frame casting. The top of the frame 708 consists of a circular disk 714 located directly beneath the nail barrel; and a disk is provided with a series of chute mouths 716 extending through the disk and entering each a nail chute 718. By means of the chutes 718, the mouths 716 communicate with individual nail stalls 720, 720 in the nail box 722. As presently explained the nails are normally retained in the stalls 720, 720 by a gate 724 which closes the latter from beneath.

As shown in Fig. 45, the chute mouths 716 are so disposed upon the disk 714 that, whenever the barrel assumes its nail discharging position with the blank 686 next the raceway, said mouths register exactly with the holes 706 leading downwardly from the nail receiving grooves in the barrel. Hence as the nails depart from the barrel they enter the mouths 716 and are conducted by the chutes 718 to their respective stalls 720 in which they are held by the gate 724.

Referring now to Figs. 45 and 50, the distributor gate 724 consists of a thin plate arranged to slide endwise (from right to left and vice versa, Fig. 45) in a dovetailed seat on the bottom of the nail box 722 (see Fig. 50). Normally the gate tends to move toward the left in Fig. 45, under the influence of a tractile spring 726 secured at one end to a stud on the gate, thence passing into a socket in the nail box in which its other end is rigidly attached. The movement of the gate by the spring 726 is limited by stop pins 728 rigid with the gate, which abut against an edge of the nail box. The gate is moved against the influence of the spring 726 (to the right, Fig. 45) through the agency of an abutment 730 which projects downwardly from the gate into the path of a striker 732 on a nail carrier hereinafter described.

When the gate occupies the position shown in Fig. 45, the striker 732 being then active, a series of holes in the gate register respectively with the stalls 720 of the nail box and permit the nails to escape therefrom. When, however, the gate has moved to the left hand limit of its movement in Fig. 45, the holes in the gate fail to register with the stalls 720 which are then closed by the gate to retain nails therein.

At certain times in the operation of the machine (see Figs. 45 and 50) a nail carrier

734 (constituting an exemplification of the nail conveying means heretofore referred to) is stationed directly beneath the nail box 722. This is the nail receiving position of the nail carrier (shown also in Fig. 40) which is moved therefrom into nail delivering position (Fig. 41) over the nail block H.

As shown in Figs. 40, 42, 45 and 50, the nail carrier 734 is circular in plan and is rotatably mounted upon an annular bracket 736 (Figs. 42 and 45) which is rigid with a nail carrier lever 738 pivoted for convenience upon a bushing encircling the left hand pricking and driving plunger 432 shown in Fig. 5 (see also Figs. 1, 2 and 4).

The nail carrier proper consists of a cylindrical block (Figs. 42 and 45) having a circular peripheral flange at its upper edge which rests upon an annulus 740 overlying the annular bracket 736. The annulus 740 is rigidly affixed to a cylindrical hub 742 encircling the nail carrier 734; and said hub has a radially extending flange 744. The annulus 740 and said flange 744 (Fig. 45) supply collectively a groove embracing the bracket 736 with a sliding fit so as to permit the nail carrier hub 742 to rotate within said bracket. The nail carrier 734 is readily removable from the hub 742 and is held rigid therewith, when in position, by means of a dowel pin 735 (see Fig. 45). Rigid with the bracket 736 is a handle 737 by which the carrier may be swung manually if desired. The striker 732 is rigidly secured to this handle 737.

Referring again to Fig. 45, the nail carrier 734 has a series of nail cups 746 having their lower ends closed by a nail carrier gate 748. When the carrier 734 is in nail receiving position (Fig. 45) each nail cup 746 registers with a nail stall 720 in the nail box 722. As the nail carrier reaches this position upon returning from the nail block H, the striker 732 impinges against the abutment 730 on the nail box gate 724 and opens the latter to permit the load of nails in the stalls 720 to be discharged into the cups 746 wherein they rest upon the nail carrier gate 748.

The gate 748 is well shown in Figs. 40, 41 and 42. It consists of a thin plate, roughly oval in outline, adjacent the lower face of the carrier and rigidly mounted at the lower end of a gate shaft 750 which is journaled vertically in the carrier (Fig. 42). Rigidly fixed to the upper end of the gate shaft 750 is a gate opening lever 752. Thus when said lever is rocked the gate is oscillated with the shaft 750. Connected at one end to the lever 752 and at the other end to a pin on the nail carrier, is a tractile spring 754 which tends to oscillate the gate 748 clockwise in Fig. 40. Such oscillation is limited by a pin 756. The gate 748 has a series of apertures 758 (see dotted lines,

Fig. 40) which, when the gate is oscillated against the spring 754, register with the nail cups 746 in the carrier and permit the nails to escape downwardly; normally, however, the spring 754 serves to hold the apertures 758 out of registry with the cups 746 and thereby to keep the latter closed. The lever 752 is automatically rocked to open the gate and liberate a load of nails, when the carrier takes position over the nail block H; and thereupon the nails drop vertically into holes in the nail block.

It has been stated hereinbefore, that the nail block H (Fig. 40) contains a series of nail receiving holes 286 having the number and disposition of a load of nails intended to be driven into a heel. Since nails are desired to be dropped vertically downward from the cups 746 of the nail carriers into said holes 286, it is important that said cups have the same number and disposition as said nail block holes 286, and that said cups be positioned, preparatory to discharging their nails, exactly above the holes 286 respectively. The nail block H (Fig. 40) has a series of seven nail holes 286 arranged in substantially horseshoe shape, and consequently it is expedient to have the load in the carrier consist of seven nails disposed in exactly the same manner. The organization of the specific machine, however, renders it convenient to deliver the nails to the carrier with their horseshoe arrangement substantially the reverse of that of the holes in the nail block, as indicated by the relative positions, in Fig. 40, of the nail block holes and the cups on the nail carrier. Hence it becomes necessary to revolve the nail carrier through a considerable angle 40 in order to bring its cups 746 into registry respectively with the nail holes 286 when the carrier takes its nail delivering position (see Fig. 41) over the nail block H.

As shown in Fig. 40 the nail carrier 734 occupies its nail receiving position, as when it is beneath the nail box 722 in Fig. 45. It is removed from this position to carry nails to the nail block H by rocking its lever 738 on its pivot. During this movement, the nail block is revolved through the required angle as suggested in the preceding paragraph, by the engagement of a segmental gear 760 on the flange 744 of the carrier, and a segmental rack 762 rigid with the top tie piece 194 of the machine frame. The co-operation of said gear and rack is such that movement of the carrier lever on its pivot, clockwise in Fig. 40, rotates the nail carrier from nail receiving position where it registers with the nail box (see Fig. 45), into nail delivering position where it registers with the nail block H, (see Fig. 41).

It will be observed in Figs. 2, 31 and 32 that the top tie piece 194 has a recess 764 of considerable dimensions, immediately

above the nail block H; and that entrance may be had to this recess from the rear of the machine (on the right Figs. 31 and 32) through an opening 766 in the rib 194^b. From time to time the recess 764 receives the turret which descends to prick or drive as shown in Figs. 31 and 32. At a time when the recess 764 is empty of the turret, the nail carrier is projected into it through the rear opening 766 in order to bring said carrier into nail delivering position over the nail block H (Fig. 41); and the progress of the carrier is arrested when it reaches that position by a part of it abutting against a stop 768 (Fig. 31) depending from the front rib 194^a of the top tie piece 194. As the carrier strikes the stop 768, the gate opening lever 752 (see Fig. 41) strikes a part 770 of the top tie piece with the result that said lever, with the gate 748, is rocked to release the nails from the carrier, they dropping thereupon into the holes in the nail block H in readiness to be driven. When thus deposited in the nail block H the nails are prevented from dropping clear through said block by nail holding springs 772 shown in detail in Figs. 23, 24, 27, 28 and 29, on Sheet 13. Each nail hole in the block H is supplied by a hollow cylinder 774 countersunk in the nail block (Fig. 24). Each cylinder is encircled by a peripheral groove 776. Communicating with the groove 776 and extending upwardly from it to the top of the cylinder 774, are three vertical spring receiving grooves 778 (Figs. 27, 28 and 29) in which respectively are seated the upper ends of leaf springs 772. Each spring 772 has laterally projecting arms 780 appropriately curved to fit snugly in the groove 776. Below the groove 776 a downward continuation 782 of each vertical groove 778 is, in part, cut clear through to the interior of the cylinder thereby permitting a portion of each spring 772 to project into said interior; and thus the springs contribute to hold a nail as shown in Fig. 29. The lower ends of the three springs 772 are held close together by the normal tension of the springs, and thus they supply a yielding support for a nail which the mere weight of the nail is not sufficient to displace, but which a driving force applied to the head of the nail readily disorganizes with the result that the nail is permitted to descend and enter a heel under the impulse of the drivers. When the drivers are withdrawn the springs resume their original positions (Fig. 29) ready to support the next nail.

The means by which the nails are supplied to the nail block having been explained, it now becomes necessary to describe the co-operation of various features of the supplying means with the other elements of the heeling machine. As regards the preferred machine, the nail feeding

125
130

mechanism is required to accommodate its operation to that of various other elements and to perform its offices with reference to the three cycles. For example, nails should 5 be in position in the nail block H before the driving operation in the second cycle; and, on the other hand, no nails should be deposited in the nail block until after the pricking operation in the first cycle. It is 10 convenient therefore to move the nail carrier into nail delivering position over the nail block during the latter part of the first cycle when the pricking awls have retreated from the nail block. A single heel and top 15 lift are attached during the three cycles and for this purpose one load only of nails is necessary to be used. It follows then that the nail separating mechanism should separate but one load of nails during the three 20 cycles and that only one load should be delivered to the carrier. In various other particulars presently disclosed the proper coaction of the nail feeding mechanism with the other elements should be provided for. 25 Referring now to Figs. 1, 2, 4, 40 and 41, the nail carrier lever 738 is connected by a rigid link 784 to the upper end of a carrier shifting lever 786 (see Figs. 2 and 4) fulcrumed at the right hand side of the rear of 30 the machine upon a stud shaft 787 mounted in a stationary bracket projecting from a standard E. Also fulcrumed upon said stud shaft is an actuating lever 789 carrying at its lower end a cam roll 790 for a carrier 35 shifting cam 792 splined on the auxiliary shaft C. Connected to the lower end of the lever 789 (see Fig. 1) is a tractile spring 794 attached at its other end to a pin on the stationary middle tie piece of the frame. 40 This spring holds the cam roll 790 against the cam 792 and, during the rotation of said cam, rocks the lever yieldingly in one direction (contra-clockwise, Fig. 1). The upper arm of said lever (see Fig. 2) has a pin 45 796 to which is attached a tractile spring 798 having its other end fastened to the carrier shifting lever 786. This spring 798 holds the upper end of the actuating lever 789 normally in contact with an adjustable 50 stop screw 800 on the shifting lever 786. The positive action of the cam 792 rocks the actuating lever 789 contra-clockwise in Fig. 2, and the latter, through the spring 798, carries the shifting lever 786 yieldingly with 55 it. As the cam 792 advances, the actuating lever 789 is rocked clockwise in Fig. 2 by its spring 794 (Fig. 1). In this manner the nail carrier is yieldingly oscillated on its pivot between its nail receiving and nail 60 delivering positions; said oscillation being limited at one extreme by the stop 768 already described (Fig. 31) and at its other extreme by a portion of the carrier abutting against a stop face 802 on the bracket 602 (Fig. 40).

The design of the carrier cam 792 is such that the carrier is moved from nail receiving position to nail delivering position, and back again, during each complete revolution of the auxiliary shaft C which as already 70 explained consumes the entire three cycles; and consequently nails are delivered to the nail block and the carrier is returned for another load once during the entire pricking, nailing and spanking operation of the 75 machine. The cam 792 is timed to throw the carrier into position over the nail block when the pricking awls have sufficiently ascended after the pricking operation in the first cycle. When the carrier is delivered 80 of its load of nails, it returns to position beneath the nail box 722 and there remains during the further operation of the machine.

It should be noted that the arrival of the 85 nail carrier in nail receiving position (Fig. 45) acts, through its striker 732 and the abutment 730 on the nail box gate, to open the latter and discharge a load of nails into the carrier; and the nail box gate is otherwise 90 preferred to be invariably closed. Also, the arrival of the carrier in nail delivering position (Fig. 41) acts, through its gate opening lever 752 and the stationary abutment 770, to open the carrier gate 748 95 and drop the nails into the nail block holes; and the nail carrier gate is otherwise preferred to be invariably closed. Thus nails are never discharged automatically from either nail box or carrier until the proper 100 moment arrives. The operator or boy may, however, at any time, open either or both of the gates 724 and 748 in order to empty the box or carrier. Since the nail carrier delivers but one load of nails during an 105 entire heeling operation, it is important that the separating mechanism remove but one load from the raceway during a like period. Provision is made, therefore, for depositing in the nail box 722 one load of nails during 110 the progress of the three cycles, and thereupon arresting the operation of the separating mechanism until it is desired to repeat the heeling operation.

Referring now to Figs. 44 and 52, the 115 operation of the supplying mechanism is immediately controlled by a positive clutch comprising a driving clutch member 804 and a driven clutch member 805. The clutch member 804 (Fig. 52) is rigidly 120 mounted upon the elongated hub of a bevel gear 807 pinned to a short shaft 808. Said gear 807 meshes with a second bevel gear 810 fixed on a power shaft 812. The latter carries also a rigid belt pulley 814 which is preferably constantly rotated, independently if desired, of the rest of the machine. The short shaft 808 is journaled in a part 125 of the frame casting and a portion of the hub of the gear 807 projects beyond the 130

end of said shaft supplying a seat for one end of the main shaft 640 of the separating mechanism. The other end of the main shaft (on the left in Fig. 52) is journaled in the frame casting. Thus the shafts, while mounted end to end, are permitted free relative rotary movement except when the clutch is engaged as presently explained.

As shown in Fig. 44, the driven clutch member 805 is mounted on the shaft 640. Projecting rearwardly from said clutch member and entering cylindrical recesses in the pawl cam 670, are pins 816. Since the pawl cam 670 is splined on the shaft 640, said pins 816 prevent the clutch member 805 from rotating on the shaft 640, but, at the same time, the pins permit said member to be moved lengthwise of the shaft toward and from the driving clutch member 804. The member 805 is moved thus by a yoke 818 having trunnion pins 820 projecting into blocks slidably mounted in an annular groove encircling said member. The yoke 818 is pinned to the lower extremity of a vertical shaft 822 (Figs. 43 and 52). Pinned to the upper end of said shaft (Fig. 51) is a clutch throwing arm 824 acted upon constantly by a tractile spring 826 which tends to rock said arm clockwise in Fig. 51, thereby tending also to rock the yoke 818 (clockwise in Fig. 52) so as to engage the clutch and start the rotation of the shaft, 640. The influence of the spring 826 is opposed in order to hold the clutch disengaged, by a latch 828 (Fig. 51) arranged to engage a lug 830 projecting upwardly from the clutch throwing arm 824. Said latch 828 is pivoted at 832 to a shipping lever arm 834 pinned to the upper extremity of a vertical shaft 835 which has pinned at its lower end the other arm 836 of the shipping lever. The latch is held normally in engagement with the lug 830 by a tractile spring 831 connected at its opposite ends to the latch 45 and the lever arm 834 respectively. The shaft 835 should not be confused with the shaft 669 (Figs. 43 and 52) to the upper and lower ends of which, respectively, are pinned the arms of the bell crank pawl driving lever 50 668. Said shafts 835 and 669 are journaled end to end in the frame casting (see Fig. 43) but are entirely independent. In like manner to the pawl driving lever, the barrel locking lever is fulcrumed on its vertical shaft 678 (Fig. 52) by having its two arms pinned respectively to the upper and lower ends of said shaft (see Fig. 43).

Referring to Fig. 51, the shipping lever 834—836 is acted upon constantly by a tractile spring 838 which tends to rock said lever clockwise in Fig. 51, and thereby to retreat the latch 828 enough to let the spring 826 engage the clutch. Thus when the spring 838 is unopposed the clutch is engaged and 65 the shaft 640 revolves. The shipping lever

834—836 is rocked contra-clockwise in Fig. 51 for disengaging the clutch through the latch 828, by means of a shipping cam 840 (Figs. 45, 50 and 52) which consists of a block fixed upon the bottom of the barrel locking plate 662. In the intermittent rotation of the nail barrel the cam 840 is brought into position to rock the shipping lever and disengage the clutch, when the blank 686 reaches its station opposite the raceway as 75 shown in Fig. 48, and thereupon the operation of the mechanism ceases. At substantially the same moment the nails are permitted to drop from the barrel into the nail box 722 as already described. The cam 840 80 remains in engagement with the shipping lever 834—836 after the mechanism is stopped. In order to start the mechanism again the latch 828 is rocked (contra-clockwise in Fig. 51) to release the clutch throwing arm 824 and permit the spring 826 to engage the clutch anew. The latch 828 is rocked to this end by means of a nail feed control lever 842 (Figs. 44, 47 and 51) the upper end of which strikes the tail of the 90 latch. After the latch has been thus rocked its acting end rests against but does not effectively engage the lug 830. The latch stands in position, however, to reengage the lug when the former is moved a short distance to the right in Fig. 51.

Referring to Figs. 2 and 4, the nail feed control lever 842 is fulcrumed on a stud 844 rigid with a standard E of the machine; and a projecting arm 846 of said lever is 100 connected by means of a tractile spring 848 to a pin on the machine frame. Said spring tends to rotate the lever 842 clockwise in Fig. 2 and to hold it in inactive position; and said spring is opposed for rocking the lever to strike the latch 828 by a cam 850 carried on the auxiliary shaft C. Once during each revolution of said auxiliary shaft (i. e. once during the three cycles) the cam 850 acts to rock the lever 842 contra-clockwise in Fig. 2, and thereby to unship the latch 828 to initiate the operation of the nail feeding mechanism.

It has already been explained that the first revolution of the shaft 640 (Fig. 44) serves 115 to bring the first nail groove on the barrel into receiving position adjacent to the raceway; and that it is expedient during said first revolution to detain the separator slide 628 to prevent the separator plucking a nail 120 from the raceway at a time when there is no groove in position to receive the nail. The separator is thus detained through the agency of its rigid pin 630 (Figs. 44 and 44^a) whereby it is connected to its lever 632. 125 As shown in Fig. 44 said pin projects through, and to some distance beyond, the lever 632.

Referring now to Figs. 44, 47 and 51; in order to detain the separator, when it is in 130

its retracted position a detent finger 852 is projected endwise (toward the right in Fig. 44; toward the left in Fig. 51) into the path of the pin 630 which tends always to move forwardly with the separator 626 under the influence of the spring 644 (Fig. 47). Said detent finger 852 is pivotally mounted upon an arm 854 which is conveniently integral (Fig. 47) with the arm 836 of the shipping lever so that whenever the shipping lever is rocked the detent finger is moved endwise. In order to preserve the proper alinement of the detent finger 852 its right hand end in Fig. 51 (left hand end in Fig. 44) is pivotally secured to a guide arm 856 loosely mounted upon the vertical shaft 822 (see Figs. 43, 44 and 51) said guide arm being merely idle and rocking only to guide the detent finger in its endwise movement.

As shown in Fig. 51, when the shipping lever 834—836 is rocked contra-clockwise by the cam 840 to stop the mechanism, the detent finger 852 is moved to the left and its detaining end is stationed in the path of the pin 630 (Fig. 44^a), where it remains when the mechanism is again started. When the mechanism is at rest the separator cam 638 holds the pin 630 in such a position that it is spaced a short distance from the detent finger 852; but when the mechanism starts the cam 638 soon becomes ineffective and the pin 630 by moving slightly strikes against and is held by said detent finger. The engaging surfaces of the pin 630 and the detent finger (see Fig. 44^a) comprises two opposed bevels which interlock and tend to bind the pin and finger together.

Shortly after the mechanism starts the shipping cam 840 departs from effective engagement with the shipping lever 834—836; and thereupon (see Fig. 51) the spring 838 tends to rock the shipping lever in such a manner as to withdraw the detent finger 852 from engagement with the pin 630. The engagement of the opposed bevels on said finger and pin is sufficiently secure, however, to prevent their being separated by the spring 838, until during the second revolution of the shaft 640 the separator cam 638 (Fig. 47) retracts the pin 630, thereby releasing the detent finger; and permits the shipping lever to rock clockwise in Fig. 51 to withdraw the detent finger. Hence as the second revolution of the shaft 640 progresses, the separator is permitted to make its forward trip to pluck a nail from the raceway and deposit it in the recently presented groove in the nail barrel.

The same movement of the shipper lever 60 which withdraws the detent finger as just described, moves the latch 828 to the right in Fig. 51 into renewed engagement with the lug 830 on the clutch throwing arm 824, so that then the shipping lever is properly connected for disengaging the clutch when

rocked by the shipping cam 840 as already explained. When the shipping cam acts thus to disengage the clutch and stop the mechanism, the latch 828 is placed in position to be unshipped by the nail feed control lever 842 whereupon the mechanism will be started anew.

Occasion frequently arises for reasons hereinafter explained for removing the nail barrel and it may happen that the nail feeding mechanism will be started when no barrel is present to receive nails. In order to prevent the removal of nails from the raceway at such times, a separator lock is provided which is effective, whenever the barrel is withdrawn and until the barrel (or another) is returned, to prevent any operative movement of the separator.

Referring to Figs. 44, 46 and 51, this lock consists of a finger 858 pivoted (in common with the detent finger 852) to the arm 854. The free end of the lock finger 858 has a tooth 860 (Fig. 51) which tends to move toward a catch plate 862 rigid with the frame casting. The barrel would be withdrawn usually only when the mechanism is at rest, *i. e.* when the detent finger 852 lies in front of the pin 630. Evidently under these circumstances, if the lock finger 858 be permitted to engage the catch plate 862 the detent finger would be maintained in front of the pin 630 even later than the first revolution of the shaft 640, and in fact until the lock finger is withdrawn.

Referring to Figs. 44 and 46 the nail barrel slide 652 has a rearwardly projecting ear 864 which, when the barrel is in position, engages a downwardly projecting pin 866 on the lock finger 858 and holds said finger out of engagement with the catch plate 862 (Fig. 51). When, however, the barrel is withdrawn, a tractile spring 868 draws the finger into engagement with the catch plate and thereby locks the separator against effective movement until the barrel is replaced.

To summarize: When the nail supplying mechanism stands at rest its parts occupy the positions shown in Fig. 48. At the appropriate time in the operation of the machine the latch 828 (Fig. 51) is shipped by the clutch throwing arm 824 and thereby the clutch of the supplying mechanism is permitted to engage, and said mechanism is started. The first revolution of the main shaft of the supplying mechanism is ineffective except to move the nail barrel through one of its steps of rotation in order to present a nail groove in position to receive a nail from the raceway. Thereupon the mechanism is in readiness to start the separation of the desired number of nails from the source of supply; and the next revolution of the shaft sends the separator forward to pluck a nail from the raceway and deposit it in a groove of the barrel, as

shown in Fig. 49. Successive operations of the separator, accompanied by successive rotary steps of the nail barrel, serve to supply the latter with its full quota of nails; and thereupon the mechanism is stopped automatically by the coöperation of the cam 840 and the shipper lever 836. The mechanism remains at rest throughout the remaining operations of the machine.

Attention has been called from time to time in the course of the preceding description to the fact that the following parts are readily removable from the machine, to wit: The nail block, the awl block, the driver block, the nail carrier, the distributer (intermediate the nail barrel and the nail carrier), the nail barrel, and the magazine raceway. One purpose of providing means for facilitating the removal of these several parts resides in the desirability of giving to a heeling machine as broad a scope of utility as possible in applying heels of various styles and sizes. It has been explained that the nail block determines the mutual relations of the nails when they are driven into a heel and hence, the desirability of having readily interchangeable nail blocks is obvious. The same is true as regards the nail carrier; and also the distributer since it is convenient to have the latter arrange the nails in their intended mutual relations before supplying them to the nail carrier. While these remarks apply to the specific illustrative device shown in the drawings, they are not to be regarded as limiting the scope of the invention to the particular embodiments herein described.

It is one of the offices of the preferred form of nail barrel to receive a predetermined number of nails from the magazine, or other source of supply, and to assist in precluding the removal from the latter of any additional nails; and the office of arranging the nails in their desired mutual relations devolves more particularly upon those parts of the mechanism which act on the nails after their departure from the barrel. It is practicable therefore to employ a single nail barrel for supplying nails to heels of various styles regardless of the different dispositions of nails which they may demand, provided said heels are intended to be attached all by the same number of nails. That is to say, when nails to the predetermined number have been received in the nail barrel they may thereafter be arranged to suit the style of heel intended to be attached. Therefore a single nail barrel may be employed to coöperate with a number of distributers, nail carriers, etc. For this reason, it is preferred to make the distributer removable from the machine independently of the nail barrel, and this is accomplished very effectively by mounting them upon independent slides as already described.

The raceway or other magazine is preferred to be readily removable to provide for expeditious changes in sizes or styles of nails. This, together with the other features of ready removal and replacement of parts, contributes to give the machine an extremely wide field of utility for attaching heels of different sizes and styles by means of variously disposed nails, in any practicable number, and having any desired size.

In order further to enhance the usefulness of the machine and to render it capable of supplying practically all demands which might be made of a heeling machine, this invention contemplates certain provisions about to be described for converting the preferred form of machine hereinbefore discussed into an automatically measuring machine or into a machine from the operation of which the measuring feature is eliminated.

In order to provide conveniently for a hand measuring operation, independent of the actuating means which serve to hold the heel in nailing position (and, if desired, to compress the heel), provision is made in the preferred machine for connecting and disconnecting the shoe jack from the jack actuating mechanism, thereby permitting the jack at desired times to be moved for measuring independently of its actuating mechanism. Evidently if the jack and its actuating mechanism were permanently connected the jack would be positively moved and the hand measuring operation would be no longer practicable. It is convenient therefore when it is desired to eliminate the measuring operation to secure the jack spindle locking nut 363 permanently against rotation relatively to the main jack spindle sleeve 305, thereby, in the manner already elucidated, securing the latter and the jack lifting frame 306 rigidly together so that said sleeve is compelled to partake of the entire vertical reciprocation of the jack lifting frame actuated by the jack actuating cam 308. Fig. 53 shows convenient means for thus permanently securing the jack spindle locking nut 363 against rotation. As shown in said figure the locking nut 363 is provided with a vertical cylindrical aperture adapted to register with a similar aperture extending through the top wall of the jack lifting frame 306. When it is desired to eliminate the measuring operation a pin 870 may be inserted in said aperture thereby preventing rotation of the locking nut, with the result already explained, of securing the main jack spindle 304, its sleeve 305 and the jack lifting frame 306 rigidly together.

Referring now to Fig. 30, the jack actuating cam 308, during one hundred eighty degrees of rotation from the position shown in said figure, will positively elevate the

jack and the shoe mounted thereon during the second cycle; and the heel will be attached in the usual manner. During this positive elevation of the jack, the heel will 5 receive its compression, which will be limited by the uppermost limit of the movement of the jack determined by the particular adjustment of the parts provided for as previously explained. During the third cycle, 10 however, the thickness of the heel is augmented by the introduction of the top lift into attaching position and consequently if the jack be then moved positively to the uppermost limit which it reached during the 15 second cycle for attaching the heel, an abnormal resistance would be offered to the final movement of the jack which might react disastrously upon the shoe or the mechanism; and also the heel and the top lift 20 would be subjected to an extraordinary compressing force which would be likely to distort them beyond repair. It is advisable, therefore, preparatory to the top lift spanking operation in the third cycle, to lower 25 slightly the shoe and its attached heel (as by turning the adjusting handle wheel 506, see Fig. 30) in order to allow for the added thickness between the nail block and jack occasioned by the insertion of the top lift. 30 As an alternative to this adjustment, preparatory to the third cycle, it would be practicable to alter the jack actuating cam 308 so as to lessen the upward throw of the jack for the spanking operation by the desired 35 distance, to allow for the top lift, and this could be conveniently effected by reducing (or it may be eliminating) the cam rise 352 of the jack actuating cam shown in Fig. 30.

40 In connection with the use of the arrangement shown in Fig. 53, it may be desirable to use an iron last or the like and to this end, such a last (of any practicable form) may be substituted for the jack shown in 45 the drawings, or else the latter could be adapted to support an iron last or jack.

An exemplification of a convenient means for converting the preferred form of machine into an automatically measuring machine is shown in Fig. 54, which will presently be referred to. This figure may well be compared with a portion of Fig. 30.

It has been explained that preliminarily 50 to the pricking operation in the first cycle, the spring 313 (Fig. 30) when compressed somewhat by the elevation of the jack lifting frame 306 acts to elevate the heel anvil 55 yielding until it abuts and rests against the heel supported in the heel carrier beneath the nail block. During the second cycle, however, said spring 313 unaided is of no effect to lift the combined weight of the shoe holding means and their table, and the heel anvil and its table; and for the purposes of the preferred form of the machine 60

it would be undesirable to have the shoe elevated by the spring 313 during the second cycle. If, however, it should be desired that the shoe be yieldingly elevated automatically to measure the heel during the 70 second cycle this could be provided for by substituting for the spring 313 and its immediately associated devices, the arrangement shown in Fig. 54. In said Fig. 54 the lug 318, which is rigid with the spindle 75 sleeve 305, has screwed into it a headed screw 872 and this screw 872 has a reduced, unthreaded portion 874, which extends downwardly through an aperture in the ear 322 on the jack lifting frame 306. On the 80 threaded portion of the screw 872 is a nut 876. Between the nut 876 and the ear 322 of the jack lifting frame, and encircling the screw 872, is a compression spring 878 which is preferably somewhat heavier than the 85 spring 313 shown in Fig. 30. With this arrangement the screw 872 is rigid with the spindle sleeve 305 through the intermediation of the lug 318. By turning the nut 876, the degree of compression of the spring 878 90 may be adjusted until it is sufficient to carry the spindle sleeve 305, the jack spindle 304 and all its associated parts, including the jack table, the jack and the shoe, yieldingly upward to measure the heel automatically 95 when the jack lifting frame 306 is elevated through its first upward step in the second cycle. When the shoe, during the course of this elevation, abuts against the heel it rests there (even though the jack lifting frame 100 306 may further ascend and compress the spring 878) until the rotation of the jack spindle locking nut is arrested, as already described. Thereupon the shoe is moved positively to grip the heel against the nail 105 block and, it may be, to compress the heel, if desired. This supplies convenient and effective means for measuring the heel automatically but if the spring 878 be of sufficient power to elevate the considerable dead 110 weight which is opposed to it, in the second cycle, said spring is likely also to impede the downward return of the parts, even though the jack lifting frame 306 be promptly retracted. This is especially likely to occur 115 during the first cycle, when the only weight opposed to the spring 878 is that of the anvil table and associated parts, without any portion of the shoe holding means and their table. It is expedient, therefore, to supply 120 means for positively moving the spindle sleeve 305 and parts connected to it downwardly with the jack lifting frame 306. This is conveniently provided for by means of a dowel-pin 880, driven through the lower 125 end of the part 874 of the screw 872, and arranged to abut against the lower face of the ear 322 of the jack lifting frame 306. Thus, when the shoe has been moved upwardly at first yieldingly and then posi- 130

tively, and, when the jack lifting frame 306 begins its return descent, the latter moves a short distance only before it strikes against the dowel-pin 880 and thereupon 5 becomes effective to pull the shoe positively downward to remove it promptly from its elevated position. Of course the dowel-pin 880 would probably prohibit a hand measuring operation but hand measurement is not 10 contemplated in connection with such an arrangement as is shown in Fig. 54.

By way of general recapitulation, the 15 operation of the preferred form of machine shown in the drawings will now be rehearsed in outline.

The first steps, preparatory to the use of the machine, comprise the selection and introduction of a nail block, awls, drivers, a nail carrier, a distributer, a nail barrel and 20 a raceway which are particularly adapted to provide nails of the desired qualifications and in the desired arrangement to suit the size and style of heel intended to be attached. When these matters have been 25 properly attended to all is in readiness to begin the use of the machine.

The boy at the rear of the machine inserts a heel and a top lift in their respective carriers and then starts the machine for the first 30 cycle by depressing his treadle. Thereupon the heel anvil ascends and holds, and if desired compresses, the heel against the nail block; the awls descend and prick holes in the heel; and then the heel anvil and the 35 awls retreat, leaving the pricked heel in its carrier. When the awls are sufficiently removed from the nail block the nail carrier is moved into nail delivering position above the latter to supply it with a load of nails.

40 When the carrier has departed a short distance from its nail receiving position beneath the distributer, the latch of the nail supplying mechanism is unshipped and the operation of said mechanism is initiated to de-

45 posit a new load of nails in the nail barrel for the next heel. The operation of the nail supplying mechanism then proceeds independently of the rest of the machine and the nail carrier may or may not return to nail

50 receiving position before the nails are permitted to depart from the nail barrel. During the first cycle, also, the heel anvil is withdrawn from its operative relation to the pricking mechanism to make way for the shoe jack. Moreover, the pricking awls are 55 replaced by the drivers. During the progress of these operations, which have been conducted under the supervision of the boy, the operator has been engaged uninterrupt-

60 edly in jacking a shoe on the jack and in, and held by, the shoe holding means, preparatory to the attachment of the heel. During this time he has no control of the machine. When the boy started the machine for the 65 first cycle he relinquished the control of the

machine in favor of the operator, who after the first cycle is ended and upon completion of his shoe adjusting duties, pushes the shoe bearing jack back into position, elevates the same manually to measure the heel, and holds 70 the heel elevated. The operator then depresses his treadle and starts the machine for the second cycle, whereupon the jack actuating means are elevated and at the proper time become rigidly locked to the jack spindle, 75 through the agency of the spindle sleeve, to elevate the shoe positively and compress the heel. The heel is held compressed while the drivers drive the nails through the pricked holes in the heel and the nails are clenched 80 inside the heel seat of the shoe. Subsequently the drivers and the shoe (the latter then carrying the heel with it) are retreated and a top lift is automatically shifted into position to register with the recently attached heel. 85

The control of the machine remains with the operator after the second cycle. In preparation for the third cycle, the operator again measures the heel by elevating the shoe 90 and its attached heel, but this time the measurement is of the heel with the projecting nail ends against the bottom of the toplift which now stands between the latter and the nail block of the spanker plate thereunder. 95 He then depresses his treadle to initiate the third cycle and during this cycle the shoe and heel are pressed toward the toplift and the projecting ends of the nails in the heel are embedded in the toplift, which becomes 100 thereby attached to the heel. The awls and drivers have no office to perform in this connection, and therefore they remain stationary. By the end of the third cycle the drivers have been replaced by the pricking 105 awls and all the parts of the machine have resumed their initial positions in readiness for a repetition of the first cycle.

There reside in a machine embodying features of this invention (severally or collectively considered) various advantages which have not been fully pointed out herein, but which will be readily recognized by those familiar with the art. 110

Nothing herein contained is to be construed as limiting this invention in the scope of its application to use in connection with the particular machine or the particular mode of operation, or both, selected for purposes of illustration and explanation. On 115 the contrary, said specific machine, as regards both its general organization and the construction of its various elements, as well as the mode of operation of said machine, may be variously altered and modified without departing from the proper field of the invention as it is defined in the subjoined claims. The alterations and modifications just referred to will be apparent to those skilled in the art. 120 125 130

In the annexed claims various terms are employed to denote relative position, relative movement, and the like; but such terms should be construed as terms of designation and not of limitation since, obviously, it is the relative character of such motion, position, and the like (as distinguished from absolute motion and position) which is alone of importance.

10 Claims—

1. A heelng machine comprising, in combination, a nail block; its supporting head; nailing means, said means and block being movable relatively toward and from each other; and a plurality of ribs at the front and rear of the head between which the relative movement between the nailing means and block occurs, said ribs acting as a guard to protect an attendant from the action of the nailing means.
2. A heelng machine comprising, in combination, a nail block; nailing means, said means being movable toward and from said block; and a trough-shaped supporting head for the nail block within the walls of which said nailing means moves and is thereby shielded.
3. A heelng machine comprising, in combination, nailing devices; a head; a nail block carried by the head; nail conveying means; and a guard rib on the head disposed between the nailing device and nail conveying means, said rib having an opening to permit the nail conveying means to convey nails to the nail block.
4. A heelng machine comprising, in combination, a head, nailing means at one side of the head; nail conveying means on another side of the head; a plurality of ribs forming a protective recess on one side of the head, said ribs being constructed and arranged to permit access to the recess by both the nailing means and nail conveying means; and appropriate actuating mechanism for said means.
5. A heelng machine comprising, in combination, nailing devices, a stationary head having a longitudinally arranged upright rib, a nail block supported by said head below the plane of the upper edge of said upright rib, a swinging nail carrier arm and its nail carrier for supplying the nail block with nails, said arm being pivotally supported to swing at one side of the machine to position the carrier above the nail block within the vertical limits of the upright rib, power operated means for swinging the said arm and carrier, and means for presenting a shoe to the nailing devices.
6. A heelng machine comprising, in combination, a stationary head having a longitudinally arranged upright rib; a nail block supported by said head; nailing devices arranged to be moved toward and from the nail block at one side and within the vertical

limits of the rib; and provision for presenting a shoe to the nailing devices.

7. A heelng machine comprising, in combination, a nail block; nail supplying mechanism in the rear of the nail block, and a nail carrier arranged to be moved laterally and rotatably for conveying nails from the supplying mechanism to the nail block.

8. A heelng machine comprising, in combination, nail supplying means; nailing devices; and a nail carrier arranged to move nails along trochoidal paths from the supplying means to the nailing devices.

9. A heelng machine comprising, in combination, heelng mechanism; and a nail carrier arranged to move nails along trochoidal paths leading from the rear of said mechanism.

10. A heelng machine comprising, in combination, heelng mechanism; and a nail carrier for conveying a group of nails in predetermined mutual relations, arranged to move each nail along a trochoidal path while preserving the mutual relations of the nails.

11. A heelng machine comprising, in combination, nailing devices; a movable nail carrier for supplying the same with nails; means for moving the carrier bodily toward the nailing devices; and means for causing the carrier to move angularly about a center within itself during such movement.

12. A heelng machine comprising, in combination, nailing devices; a movable nail carrier for supplying the same with nails; and provision for giving said carrier motion compounded of translation and rotation.

13. A heelng machine comprising, in combination, heelng mechanism; a revolubly supported nail carrier arranged for bodily movement; gear teeth on the carrier; and a stationary rack to engage said teeth.

14. A heelng machine comprising, in combination, nailing devices; a nail magazine in the rear of the nailing devices; means for receiving nails singly from the magazine and arranging a predetermined number of them as a group in predetermined mutual relations; and conveying means to conduct nails so arranged to the nailing devices and to change the disposition of the group within the conveying means as a whole while preserving the mutual relations of the nails.

15. A heelng machine comprising, in combination, nailing devices; a nail magazine arranged to supply nails singly; means for arranging nails so supplied, in a group; and conveying means intermediate the nailing devices and said arranging means for changing the disposition of a group of nails within the conveying means while conveying the same to the nailing devices by a path leading from the rear of said devices.

16. A heelng machine comprising, in combination, nailing devices; a nail magazine arranged to supply nails in the rear of the

nailing devices; a pivoted carrier to receive nails from the magazine and to supply them to said devices; means for moving the carrier on its pivot through a given angle; and means for rotating the carrier about a center within itself through a greater angle to determine the disposition of the nails upon presentation to said devices.

17. A heelng machine comprising, in combination, nailing devices; a pivoted nail carrier to supply nails thereto; means for moving the carrier on its pivot through an acute angle; and means for rotating the carrier about a center within itself through an obtuse angle to determine the disposition of nails when acted upon by the nailing devices.

18. A heelng machine comprising, in combination, heelng mechanism including a jack; a nail block carrying head; and a work carrier disposed adjacent to the face of the head nearest to the jack, and having supporting means provided on another part of the head remote from said face.

19. A heelng machine comprising, in combination, heelng mechanism; a head; and a work carrier disposed beneath the head but supported upon a side of said head.

20. A heelng machine comprising, in combination, heelng mechanism; a work carrier; and a head to support said carrier, constructed to taper laterally toward the carrier.

21. A heelng machine comprising, in combination, heelng mechanism; a work carrier; a head having a face oblique to the plane of the carrier; and supporting means for the carrier on said face.

22. A heelng machine comprising, in combination, heelng mechanism; a heel carrier and a top lift carrier; and size and position adjusting mechanisms for said carriers respectively, oppositely disposed on the outer sides of the carriers.

23. A heelng machine comprising, in combination, heelng mechanism including a jack arranged for supporting a shoe in inverted position; and a work carrier having a supporting bracket connected therewith and disposed at an angle to the heel seat of the shoe.

24. A heelng machine comprising, in combination, heelng mechanism including a jack arranged for supporting a shoe in inverted position; a work carrier; and means including slides having rack and pinion connections for effecting size adjustment of the carrier, said means being offset from the carrier so as to be in the rear of the heel end of a shoe so supported.

25. A heelng machine comprising, in combination, heelng mechanism including a jack arranged for supporting a shoe in inverted position; a work carrier having breast and back stops; and means including slides having rack and pinion connections for adjusting said stop and means for ad-

justing the carrier bodily longitudinally of a shoe so supported, said means being offset laterally to one side of the carrier.

26. A heelng machine comprising, in combination, heelng mechanism including a jack arranged for supporting a shoe in inverted position; a heel carrier and a top lift carrier; and size and position adjusting mechanisms for said carriers respectively, offset laterally on opposite sides of said carrier.

27. A heelng machine comprising, in combination, heelng mechanism; a work carrier; means accessible from one side of the machine for effecting size adjustment; and means accessible from the other side of the machine for effecting position adjustment.

28. A heelng machine comprising, in combination, heelng mechanism; a work carrier; means for adjusting the carrier laterally with relation to the heelng mechanism; means accessible from one side of the machine for effecting size adjustment; and means accessible from the other side of the machine to effect adjustment of the carrier endwise with relation to the heelng mechanism.

29. A heelng machine comprising, in combination, nailing mechanism; a heel carrier; a top lift carrier; actuating means for positively moving said carriers alternately into operative relation to the nailing mechanism; and yielding means for cushioning the movement by said actuating means in one direction.

30. A heelng machine comprising, in combination, nailing mechanism; a heel carrier; a top lift carrier; actuating means for positively moving said carriers alternately into one and the same operative relation to the nailing mechanism; and adjustable stops for altering the path of movement of the carriers.

31. A heelng machine comprising, in combination, nailing mechanism; a work carrier; means for positively moving the carrier into and out of operative relation with the nailing mechanism; and means for cushioning the movement of the carrier in one direction.

32. A heelng machine comprising, in combination, a heel carrier; a toplift carrier; actuating means for moving the carriers; and a rectilinear track parallel with, above and disposed obliquely to the plane of the carriers, upon the outer surface of which they are moved and supported.

33. A heelng machine comprising, in combination, heelng mechanism; a heel carrier; a toplift carrier connected to the heel carrier; and actuating means including a positively actuated lever, and a second lever intermediate the same and the toplift carrier; an adjustable stop on one lever for the

other; and means for holding the latter against said stop.

34. A heelng machine comprising, in combination, a work carrier; and size and position adjusting means for the carrier accessible respectively from opposite sides of the carrier.

35. A heelng machine comprising, in combination, nailing mechanism; a work carrier including breast stop faces and side gripping faces; means including slides having rack teeth and an idle gear operatively connecting said rack teeth for adjusting said faces positively toward and from each other; and an independent back stop, said parts being constructed and arranged to permit a simultaneous bodily movement.

36. A heelng machine comprising, in combination, nailing mechanism; a work carrier including breast stop faces and side gripping faces; means including slides having rack teeth and an idle gear operatively connecting said rack teeth for adjusting said faces positively toward and from each other; and independent back stop movable toward and from the breast stop faces, and provision for permitting simultaneous movement of said jaws and back stop after clamping the work.

37. A heelng machine comprising, in combination, nailing mechanism and a work carrier including clamping jaws arranged for reciprocal movement in a straight line; means including slides having rack teeth and an idle gear operatively connecting said rack teeth for positively moving said jaws; a movable back stop to coöperate with said jaws, and provision for permitting simultaneous movement of said jaws and back stop after clamping the work.

38. A heelng machine comprising, in combination, heelng mechanism and a work carrier including clamping jaws; a coöperating back stop; means for moving the back stop toward and from the clamping jaws; and independent means for moving the jaws toward and from the back stop.

39. A heelng machine comprising, in combination, heelng mechanism; and a work carrier including a back stop, clamping jaws, means for moving the back stop, and provision for permitting the jaws to move with the back stop in one direction.

40. A heelng machine comprising, in combination, nailing mechanism; and a work carrier including clamping jaws, slides carrying said jaws, racks and pinion connections between the slides for transmitting movement of one to the other, a back stop having a straight edge arranged to coöperate with the jaws, and means for holding said parts yieldingly toward each other.

41. A heelng machine comprising, in combination, nailing mechanism and a work

carrier including breast stop faces; side gripping faces; slides carrying said stop faces and gripping faces; rack teeth formed on said slides; an idle pinion between the slides and engaging the rack teeth thereon; and a straight edged back stop to coöperate therewith, said parts being constructed and arranged to bear yieldingly upon the work when placed within them.

42. A heelng machine comprising, in combination, heelng mechanism; a plurality of movable slides; a breast stop projecting laterally from one of said slides; a back stop projecting laterally from another slide; means for adjusting one of said slides independently of the other; and means for adjusting both slides together to effect position adjustment of the work.

43. A heelng machine comprising, in combination, heelng mechanism; a work carrier comprising a plurality of slides carrying breast stops and a back stop arranged for size adjustment; means acting yieldingly to maintain said stops in work engaging position; means for adjusting said carrier to move the work bodily with relation to the heelng mechanism; and means for moving the carrier in a line transversely to the direction of said bodily movement.

44. A heelng machine comprising, in combination, pricking means, nailing means and toplift spanking means arranged to act in succession; provision for starting the machine at three different times to initiate the operations of said three means respectively; and provision for stopping the machine at the end of each of said operations.

45. A heelng machine comprising, in combination, pricking means, nailing means and toplift spanking means; a controller on one side of the machine for starting the same to initiate the pricking operation; a controller on the other side of the machine for starting the same to initiate the nailing and spanking operations; and provision for stopping the machine automatically at the end of each operation.

46. A heelng machine comprising, in combination, pricking mechanism; nailing mechanism including a jack; and starting and stopping mechanism to start the pricking operation and for stopping the machine after the pricking operation, the jack remaining stationary in the interval.

47. A heelng machine comprising, in combination, a notched nail block; a supporting head therefor; and means for holding the nail block rigid with the head, including a rotatable wedge for engaging the notch and means under the control of the operator for engaging and disengaging the wedge and notch.

48. A heelng machine comprising, in combination, a head, a nail block sustained

thereby, nail drivers, means to move the drivers toward and from the block, and a longitudinally arranged rib on the head extending adjacent the path of movement of the drivers and substantially parallel thereto, whereby it is adapted to guard an attendant from the action of the drivers.

49. A heeling machine comprising, in combination, a stationary head, a nail block sustained thereby, drivers above the head movable relatively thereto, and a longitudinally arranged rib extending upwardly from the head adjacent to and in the direction of the path of movement of the drivers and acting as a shield therefor.

50. A heeling machine comprising, in combination, a head carrying a nail block, means for holding the same against movement, nailing devices movable in opposition to said block, a longitudinally arranged rib on said head arranged to sustain pressure on the nail block and also extending adjacent the path of movement of said nailing de-

vices thereby acting as a guard, and actuating means for said nailing devices.

25

51. A heeling machine comprising, in combination, a work support, a nail block carrying head above the work support, a work carrier disposed adjacent the under faces of the nail block and the head and above the work support, and supporting means for said work carrier provided on a part of the frame remote from said under faces of the nail block and the head.

52. In a heeling machine, the combination, 35 with nailing means and a nail carrier, of means to move said carrier yieldingly both toward and from said nailing means.

In testimony whereof, I have signed my name to this specification, in the presence 40 of two subscribing witnesses.

ERASTUS WOODWARD.
